CUP DISPENSERS

Joseph F. Lotspeich, Flor dell Hills, Mo., assignor, by
mesne assignments, to National Rejectors, Inc., St.
Louis, Mo., a corporation of Missouri

Filed Oct. 6, 1958, Ser. No. 765,669
12 Claims. (Cl. 221—4)

This invention relates to improvements in cup dispensers. More particularly, this invention relates to improvements in cup dispensers for coin-operated, drink-vending machines.

It is therefore an object of the present invention to provide an improved cup dispenser for coin-operated, drink-vending machines.

Cup dispensers for coin-operated, drink-vending machines are important and useful devices, and they are meeting ever-increasing acceptance. One defect in present cup dispensers for coin-operated, drink-vending machines is the inability of those cup dispensers to accommodate cups of different diameters unless and until some of the cup-separating parts of those cup dispensers are removed and are supplanted by replacement cup-separating parts. While the removal and replacement of the cup-separating parts of cup dispensers is easily accomplished in a factory, that removal and replacement is not so easily accomplished by the operators of coin-operated, drink-vending machines. Moreover, the need of keeping on hand a supply of replacement cup-separating parts adds inventory problems to the already numerous problems of operators of coin-operated, drink-dispensing machines. The present invention obviates those problems by providing a cup dispenser which has stack-supporting fingers that can respond to the movement of an adjusting lever to accommodate and support cups having different diameters. As a result, there is no need of removing and replacing any of the cup-separating parts of the cup dispenser of the present invention when cups having larger or smaller diameters are to be dispensed; it only being necessary to shift the position of the adjusting lever. It is therefore an object of the present invention to provide a cup dispenser for coin-operated, drink-vending machines which has stack-supporting fingers that can respond to the setting of an adjusting lever to accommodate and support cups having different diameters.

The adjusting lever for the cup dispenser provided by the present invention is pivoted to rotate adjacent a dial. That lever is made relatively long, and that dial is made to subtend a large angle; and consequently that lever and dial make it possible to set the positions of the stack-supporting fingers with precision and accuracy. It is therefore an object of the present invention to provide a relatively long adjusting lever that is pivoted to rotate adjacent a dial that subtends a large angle.

Another defect of present cup dispensers is the inability of those cup dispensers to accommodate and separate cups having different rim thicknesses, unless and until some of the cup-separating parts of those cup dispensers are removed and are supplanted by replacement cup-separating parts. The present invention obviates all need of removing and replacing any of the cup-separating parts of the cup dispenser, and thereby obviates the problems connected with that removal and replacement by providing stack-supporting fingers that can be moved vertically relative to the cup-separating fingers of the cup dispenser by the shifting of a cam. That vertical movement of the stack-supporting fingers enables the cup dispenser to accommodate and separate cups having thick rims, thin rims or rims of intermediate thickness. It is therefore an object of the present invention to provide a cup dispenser for coin-operated, drink-vending machines that has stack-supporting fingers which can respond to the shifting of a cam to move vertically relative to the cup-separating fingers of that cup dispenser.

2

The cam that adjusts the vertical positions of the stack-supporting fingers of the cup dispenser has shallow, inclined rises thereon; and those shallow rises require the cam to be shifted appreciable distances to change the vertical positions of the stack-supporting fingers. This need of shifting the cam appreciable distances is desirable because it keeps that shifting from being a critical adjustment; and, in fact, it makes that shifting an adjustment that is within the capabilities of most persons. It is therefore an object of the present invention to provide the cam, that adjusts the vertical positions of the stack-supporting fingers, with shallow, inclined rises.

The cam that adjusts the vertical positions of the stack-supporting fingers, of the cup dispenser provided by the present invention, carries a set screw; and that set screw not only locks the cam in position, but also serves as a visual indication of the vertical positions of the stack-supporting fingers. It is therefore an object of the present invention to provide the cam, that adjusts the vertical positions of the stack-supporting fingers of a cup dispenser, with a set screw that can lock the cam in position and that can also serve as a visual indication of the vertical positions of those stack-supporting fingers.

The cup dispenser provided by the present invention has a turret in which a number of stacks of cups can be supported, and that turret normally holds one of those stacks of cups in register with the stack-supporting fingers of that cup dispenser. Shortly before the last of the cups of that stack of cups has been dispensed, a turret-advancing mechanism automatically rotates the turret to dispose a fresh stack of cups in register with those stack-supporting fingers. Shortly before the last of the cups in that stack of cups has been dispensed, the turret-advancing mechanism will again automatically rotate the turret to move a fresh stack of cups into register with the stack-supporting fingers. That turret-advancing mechanism includes a Geneva gear, and that gear assures precise and accurate advancements of the turret. As a result, the various stacks of cups carried by the turret are always precisely indexed into register with the stack-supporting fingers. It is therefore an object of the present invention to provide a cup dispenser with a turret-advancing mechanism that includes a Geneva gear.

The cup dispenser provided by the present invention has a feeler which normally engages the stack of cups in register with the stack-supporting fingers, and that feeler causes the turret-advancing mechanism to index the turret when it no longer feels that stack of cups. That cup dispenser has a second feeler which normally engages that stack of cups at a point below the point where the first feeler engages that stack of cups, and that second feeler actuates an empty switch when it no longer feels that stack. This means that the first feeler will cause successive indexing of the turret without any actuation of the empty switch, and that the second feeler will actuate the empty switch only when the cup dispenser is out of cups.

The feelers for the cup dispenser provided by the present invention are moved out of engagement with the stack of cups during every cycle of the cup dispenser. This is desirable because it keeps those feelers from being impediments to the downward movement of the cups in the stacks of cups toward the stack-supporting fingers of the cup dispenser. However, before the end of the cycle of the cup dispenser, both of those feelers are permitted to move toward, and feel for the presence of, cups in the stack of cups.

The cup dispenser provided by the present invention has a gear housing, a cam housing, and a motor housing. That gear housing is formed so the cam housing can be set at any one of three faces thereof and so that motor housing can be set at any one of said faces thereof. This means that there are three possible positions wherein the

cam housing can engage the gear housing and there are three possible positions wherein the motor housing can engage the gear housing. In addition, where desired, the cam housing and the motor housing can be mounted in tandem; with that cam housing engaging the gear housing. This makes it possible to arrange the cam housing, the gear housing and the motor housing in many different ways; and, therefore, it makes it possible to mount the cup dispenser of the present invention in many places in coin-operated, drink-vending machines where other cup dispensers cannot be mounted. It is therefore an object of the present invention to provide a cup dispenser with a gear housing that has several faces to which a cam housing or a motor housing can be secured, individually or when mounted in tandem.

Other and further objects and advantages of the present invention should become apparent from an examination of the drawing and accompanying description.

In the drawing and accompanying description, several preferred embodiments of the present invention are shown and described but it is to be understood that the drawing and accompanying description are for the purpose of illustration only and do not limit the invention and that the invention will be defined by the appended claims.

In the drawing, FIG. 1 is a partially cut-away, perspective view of one preferred embodiment of cup dispenser that is made in accordance with the principles and teachings of the present invention and it shows the normal positions which the movable components occupy when only a few cups are held in the cup-separating head.

FIG. 2 is a partially broken, side elevational view of the cup dispenser of FIG. 1, and it shows that cup dispenser after the movable components thereof have passed through approximately one quarter of a cycle.

FIG. 3 is a vertical section through the cup dispenser of FIGS. 1 and 2, and it is taken along the plane indicated by the line 3—3 in FIG. 2.

FIG. 4 is a plan view of the cup-separating head, the gear housing, the cam housing and the motor housing of the cup dispenser of FIGS. 1 and 2, and it shows the movable components of that cup dispenser in the positions they occupy in FIG. 2.

FIG. 5 is a vertical section through a portion of the center of the cup-carrying turret, pivot and driven member of the cup dispenser of FIGS. 1 and 2.

FIG. 6 is a sectional view in plan of the turret of the cup dispenser of FIGS. 1 and 2, and it is taken along the plane indicated by the line 6—6 in FIG. 2.

FIG. 7 is a sectional view in plan through the cup-separating head of the cup dispenser of FIGS. 1 and 2, it is taken along the plane indicated by the line 7—7 in FIG. 2, it shows the normal positions of the cup-separating fingers and of the stack-supporting fingers and of the finger-moving abutments by solid lines, and it shows a first moved position of those abutments by dotted lines.

FIG. 8 is a sectional view in plan that is taken along the plane indicated by the line 7—7 in FIG. 2, and it shows the positions which the cup-separating and stack-supporting fingers and the finger-moving abutments occupy when the movable components of the cup dispenser are in the positions shown by FIG. 2.

FIG. 9 is a sectional view in plan that is taken along the plane indicated by the line 7—7 in FIG. 2, and it shows the positions of the cup-separating and stack-supporting fingers and of the finger-moving abutments after the movable components of the cup dispenser have passed through one half of their cycle.

FIG. 10 is a sectional view in plan that is taken along the plane indicated by the line 7—7 in FIG. 2, and it shows the cup-separating and stack-supporting fingers and the finger-moving abutments in the positions which they occupy in FIG. 8, but it shows the stack-supporting fingers after they have been set to accommodate larger diameter cups.

FIG. 11 is a vertical section through part of the cup-separating head of the cup dispenser of FIGS. 1 and 2, and it shows one of the upper cup-separating fingers that is rotatable but that is held against vertical movement.

FIG. 12 is a vertical section through another part of the cup-supporting head of the cup dispenser of FIGS. 1 and 2, and it shows one of the stack-supporting fingers.

FIG. 13 is a partially broken, perspective view of the gear housing for the cup dispenser of FIGS. 1 and 2, and of some of the components associated with that gear housing.

FIG. 14 is a partially broken, plan view of the driving and driven elements of the Geneva gear used in the cup dispenser of FIGS. 1 and 2 and of a latch used with that driven element.

FIG. 15 is a vertical section through part of the cup dispenser of FIGS. 1 and 2, and it is taken along the plane indicated by the line 15—15 in FIG. 14.

FIG. 16 is a vertical section through another part of the cup dispenser of FIGS. 1 and 2, and it is taken along the plane indicated by the line 16—16 in FIG. 14.

FIG. 17 is a plan view of the driving and driven elements used with the cup dispenser of FIGS. 1 and 2 when that cup dispenser uses a larger cup-carrying turret.

FIG. 18 is a side elevational view of one stack-supporting finger and of one upper and one lower cup-separating finger, and it is taken along the plane indicated by the line 18—18 in FIG. 8.

FIG. 19 is a side elevational view similar to FIG. 18, but it shows the stack-supporting finger after it has been moved downwardly to accommodate cups having deeper rims.

FIG. 20 is a sectional view in plan, and it is taken along the plane indicated by the line 20—20 in FIG. 2.

FIG. 21 is a partially sectioned, partially broken-away, front elevational view, on a large scale, of a detail of the cup-separating head of the cup dispenser of FIGS. 1 and 2.

FIG. 22 is a vertical section through the portion of the cup-separating head shown in FIG. 21.

FIG. 23 is a perspective view of a positioning ring used in the cup-separating head of the cup dispenser of FIGS. 1 and 2.

FIG. 24 is a front elevational view of an indicating panel used with the cup-separating head of the cup dispenser of FIGS. 1 and 2.

FIG. 25 is a front elevational view of a cam ring used in the cup-separating head of the cup dispenser of FIGS. 1 and 2.

FIG. 26 is a partially sectioned, side elevational view of a portion of the cup-separating head of the cup dispenser of FIGS. 1 and 2, and it shows the movable components thereon in the positions they occupy in FIG. 2.

FIG. 27 is a partially sectioned, side elevational view similar to FIG. 26, but it shows the movable components in their normal positions.

FIG. 28 is a partially sectioned plan view of the gear housing, part of a cam housing, and part of the cup-separating head of the cup dispenser of FIGS. 1 and 2, and it shows by solid lines the positions which the movable components occupy in FIG. 2 and it shows by dotted lines the positions which the cup-engaging feelers occupy when cups do not block their inward movement.

FIG. 29 is a sectional view in plan through the gear housing of the cup dispenser of FIGS. 1 and 2 and through one of the two cam housings associated with that gear housing.

FIG. 30 is a sectional end view through the said one cam housing of FIG. 29, and it is taken along the plane indicated by the line 30—30 in FIG. 29.

FIG. 31 is a sectional end view through the shaft and one of the cams in the said one cam housing of FIG. 29, and it is taken along the plane indicated by the line 31—31 in FIG. 29.

FIG. 32 is a partially sectioned, partially broken-away

plan view of the gear housing of the cup dispenser of FIGS. 1 and 2, and it shows some of the movable components associated with that gear housing after they have passed through approximately one quarter of a cycle,

FIG. 33 is a vertical section through the driving and driven elements of a modified form of cup dispenser that is made in accordance with the principles and teachings of the present invention,

FIG. 34 is another vertical section through the driving and driven elements of FIG. 33,

FIG. 35 is a vertical section through a modified cup-separating head usable with the cup dispenser of FIGS. 1 and 2,

FIG. 36 is a sectional view in plan through the cup-separating head of FIG. 35, and it is taken along the plane indicated by the line 36—36 in FIG. 35,

FIG. 37 is a partially broken, plan view of part of the cup-separating head of the cup dispenser of FIGS. 1 and 2, and it shows the movable components of that cup dispenser in the positions they occupy in FIG. 2,

FIG. 38 is a plan view of one of the upper cup-separating fingers and springs of the cup dispenser of FIGS. 1 and 2,

FIG. 39 is a side elevational view of the cup-separating finger and spring of FIG. 38,

FIG. 40 is a plan view of one of the lower cup-separating fingers of the cup dispenser of FIGS. 1 and 2,

FIG. 41 is a side elevational view of the cup-separating finger of FIG. 40,

FIG. 42 is a bottom view of the cup-separating finger of FIGS. 40 and 41,

FIG. 43 is a plan view of one of the stack-supporting fingers and springs of the cup dispenser of FIGS. 1 and 2,

FIG. 44 is an elevational view of the left-hand side of the finger and spring of FIG. 43,

FIG. 45 is an elevational view of the right-hand side of the finger and spring of FIG. 43,

FIG. 46 is a side elevational view of one of the lower cup-separating fingers used in the cup-separating head of FIGS. 35 and 36,

FIG. 47 is a side elevational view of one of the rotatable cup separating fingers that is pivoted in, but is held against vertical movement relative to, the cup-separating head of FIGS. 35 and 36,

FIG. 48 is a sectional view in plan through the finger of FIG. 47, and it is taken along the plane indicated by the line 48—48 in FIG. 47,

FIG. 49 is a diagrammatic plan view of the cup-separating head and fingers of the cup dispenser of FIGS. 1 and 2, and it shows those fingers in the positions they occupy when the movable components of the cup dispenser occupy the positions shown by FIG. 1,

FIG. 50 is a diagrammatic elevational view showing the cup-supporting closure of the cup dispenser of FIGS. 1 and 2, and also showing three cups plus three of the fingers of FIG. 49, and it is taken along the broken plane indicated by the line 50—50 in FIG. 49,

FIG. 51 is a diagrammatic plan view of the cup-separating head and fingers of FIG. 49, and it shows those fingers in the positions they occupy after the movable components of the cup dispenser have passed through approximately one eighth of a cycle,

FIG. 52 is a diagrammatic elevational view showing two cups plus three of the fingers of FIG. 51, and it is taken along the broken plane indicated by line 52—52 in FIG. 51,

FIG. 53 is a diagrammatic plan view of the cup-separating head and fingers of FIG. 49, and it shows those fingers in the positions they occupy when the movable components of the cup dispenser are in the positions they occupy in FIG. 2,

FIG. 54 is a diagrammatic elevational view showing two cups plus three of the fingers in FIG. 53, and it is taken along the broken plane indicated by the line 54—54 in FIG. 53,

FIG. 55 is a diagrammatic plan view of the cup-separating head and fingers of FIG. 49, and it shows those fingers in the positions they occupy when the movable components of the cup dispenser have passed through one half of a cycle,

FIG. 56 is a diagrammatic elevational view showing two cups plus three of the fingers of FIG. 55, and it is taken along the broken plane indicated by the line 56—56 in FIG. 55,

FIG. 57 is a diagrammatic plan view of the cup-separating head and fingers of FIG. 49, and it shows those fingers in the positions they occupy when the movable components of the cup dispenser have passed through approximately three quarters of a cycle,

FIG. 58 is a diagrammatic elevational view showing two cups plus three of the fingers of FIG. 57, and it is taken along the broken plane indicated by the line 58—58 in FIG. 57,

FIG. 59 is a diagrammatic plan view of the cup-separating head and fingers of FIG. 49, and it shows those fingers in the positions they occupy when the movable components of the cup dispenser have passed through approximately seven eighths of a cycle,

FIG. 60 is a diagrammatic elevational view showing two cups plus three of the fingers in FIG. 59, and it is taken along the broken plane indicated by the line 60—60 in FIG. 59,

FIG. 61 is a diagrammatic plan view of the cup-separating head and fingers of FIGS. 35 and 36, and it shows those fingers in their normal position,

FIG. 62 is a diagrammatic elevational view of three cups plus three of the fingers of FIG. 61, and it is taken along the broken plane indicated by the line 62—62 in FIG. 61,

FIG. 63 is a diagrammatic plan view of the cup-separating head and fingers of FIG. 61, and it shows those fingers in the positions they occupy when the movable components of the cup-separating head of FIGS. 35 and 36 have passed through approximately one quarter of a cycle,

FIG. 64 is a diagrammatic elevational view showing two cups plus three of the fingers of FIG. 63, and it is taken along the broken plane indicated by the line 64—64 in FIG. 63,

FIG. 65 is a diagrammatic plan view of the cup-separating head and fingers of FIG. 61, and it shows the positions those fingers occupy when the movable components of the cup-separating head of FIGS. 35 and 36 have passed through approximately one half of a cycle,

FIG. 66 is a diagrammatic elevational view showing two cups plus three of the fingers of FIG. 65, and it is taken along the broken plane indicated by the line 66—66 in FIG. 65,

FIG. 67 is a diagrammatic plan view of the cup-separating head and fingers of FIG. 61, and it shows the positions of those fingers after the movable components of the cup-separating head of FIGS. 35 and 36 have passed through approximately five eighths of a cycle,

FIG. 68 is a diagrammatic elevational view showing two cups plus three of the fingers of FIG. 67, and it is taken along the broken plane indicated by the line 68—68 in FIG. 67,

FIG. 69 is a diagrammatic plan view of the cup-separating head and fingers of FIG. 61, and it shows the positions of those fingers after the movable components of the cup-separating head of FIGS. 35 and 36 have passed through approximately three quarters of a cycle,

FIG. 70 is a diagrammatic elevational view of two cups plus three of the fingers of FIG. 69, and it is taken along the broken plane indicated by the line 70—70 in FIG. 69,

FIG. 71 is a diagrammatic plan view of the cup-separating head and fingers of FIG. 61, and it shows the positions of those fingers after the movable components of the cup-separating head of FIGS. 35 and 36 have passed through approximately seven eighths of a cycle,

FIG. 72 is a diagrammatic elevational view showing two cups and three of the fingers of FIG. 71, and it is taken along the broken plane indicated by the line 72—72 in FIG. 71.

FIGS. 73 through 93 are diagrammatic plan views showing the gear housing of the cup dispenser of FIGS. 1 and 2 as it is associated in various arrangements with the motor housing and one or more cam housings of that cup dispenser.

Gear Housing and Associated Components

Referring to the drawing in detail, the numeral 100 denotes a supporting plate which has a hard, wear-resistant, upper surface. As indicated particularly by FIG. 20, the plate 100 is of rectangular configuration in plan. That plate has a downwardly extending cylindrical flange 102 which defines and encircles a discharge opening 104 of circular configuration. The opening 104 is made larger than the diameter of the largest cup to be dispensed by the cup dispenser of the present invention. As indicated particularly by FIG. 20, the opening 104 is adjacent one end of the plate 100; and, as indicated particularly by FIG. 3, the flange 102 merges smoothly into the lower face of the plate 100.

Two guide plates, which are generally Z-shaped in cross section, are denoted by the numeral 106; and each of those guide plates has a horizontal lower flange 108 that rests upon and is supported by the supporting plate 100. Each of those guide plates has a horizontally-directed vertical wall 110 that extends upwardly from the horizontal flange 108. An upper horizontal flange 112 extends inwardly from the upper edge of the wall 110. The guide plates 106 are set at opposite sides of the supporting plate 100 with their flanges 112 confronting, and extending toward, each other. Adjacent one end of each of the horizontal upper flanges 112 of the guide plates 106 is a vertically-extending wall 114 which is spaced inwardly of the wall 110, all as shown by FIG. 20. Each of the horizontal flanges 112 is narrow from the left-hand end thereof to a point beyond the longitudinal center thereof, as those horizontal flanges are viewed in FIG. 20; but those flanges are wider to the right of that longitudinal center line. The vertically-extending walls 114 project upwardly from the innermost edges of the wide portions of the flanges 112. Each of the walls 114 is provided with two vertically-extending, stiffening flanges 116, and those flanges project outwardly from the walls 114. Each of the walls 114 has a number of holes 118 which are intended to receive aligning studs, and each of those walls also has a number of holes 120 which are intended to receive fasteners, such as crews. The openings 118 and 120 are shown particularly by FIG. 2.

Two thin strips which have hard, wear-resistant surfaces at the inner faces thereof are denoted by the numeral 122. Those strips are disposed adjacent the inner faces of the vertical walls 110 of the guide plates 106, as shown particularly by FIG. 3. The lowermost edges of the strips 122 rest upon, and intimately engage, the upper surface of the support 100. An elongated guide plate 124, of L-shaped cross section, is fixedly secured to the right-hand guide plate 106, as the cup dispenser is viewed in FIG. 3; and the guide plate 124 can be secured to the right-hand guide plate 106 by suitable fasteners, such as rivets. The guide plate 124 fixedly holds one of the strips 122 in abutting engagement with the right-hand guide plate 106. An elongated guide plate 126, of L-shaped cross section, fixedly holds the other strip 122 in abutting engagement with the left-hand guide plate 106. The guide plate 126 will be fixedly secured to the left-hand guide plate 106 by fasteners, such as rivets. An ear 128 is formed on the L-shaped guide plate 126 adjacent one end of that guide plate, and that ear projects inwardly from the inner wall of that guide plate and extends toward the guide plate 124.

Fasteners 129 extend downwardly through openings in

the horizontal flanges 108 of the guide plates 106 and seat in openings in the plate 100. Aligned openings 131 are provided in the horizontal flanges 108 of the guide plates 106 and in the supporting plate 100; and those openings accommodate fasteners which can secure the cup dispenser to a frame or other supporting structure in a vending machine.

The numeral 130 denotes a closure which is generally rectangular and which is generally flat. As indicated particularly by FIG. 20, the rear edge 132 of that closure is arcuate, and that rear edge has an arcuate cam surface 134 projecting upwardly from it. The cam surface 134 has a bent end 135 and has a straight end 137; and the straight end 137 terminates at a point to the right of the ear 128 on guide plate 126, as the cam surface 134 is viewed in FIG. 3. The rear edge 132, and the major portion of the cam surface 134, are concentric with a shaft 230, shown in FIG. 20, when that closure is in the position indicated by dotted lines in FIG. 20. An ear 136 is provided on the closure 130 adjacent the front edge of that closure, and a helical extension spring 138 has one end thereof hooked through an opening in that ear. The other end of the spring 138 is attached to the ear 128 on the guide plate 126; and that spring biases the closure 130 from the dotted line position to the solid line position shown in FIG. 20. A stop 140 of resilient material, such as rubber or the like, is secured to the support 100 by fasteners 142. The stop 140 is in register with the straight end 137 of the arcuate cam 134; and that stop cushions the stopping of the closure 130 as that closure moves from the dotted line position to the solid line position shown in FIG. 20.

The numeral 144 denotes a gear housing which, in plan view, is generally square in configuration. That gear housing will preferably be formed as a casting; it has one open side, and it has the other three sides thereof bounded by vertical walls. That portion of the top of the gear housing which is adjacent the open side of that housing is arcuate and is concave, as shown particularly by FIGS. 13 and 32. That portion of the top of the gear housing is complementary to, and can accommodate, part of the periphery of the cup-separating head of the cup dispenser, as shown particularly by FIGS. 1 and 28. Each of the said three vertical walls of the gear housing 144 has a large shaft-receiving opening 146 and three bosses 150; and openings 148 extend through those bosses and through those vertical walls. Two of the three vertical walls of the gear housing 144 are equipped with horizontally-extending aligning studs 152; and those studs are dimensioned and positioned to extend into the aligning openings 118 in the vertical walls 114 of the guide plates 106. Each of those two vertical walls of the gear housing 144 also has two tapped openings 155 below the studs 152; and fasteners 153 extend through the openings 120 in the vertical walls 114 of the guide plates 106 and seat in those tapped openings. Each of the said two vertical walls of the gear housing 144 also has a countersunk opening intermediate the tapped openings 155. Those countersunk openings accommodate flat-headed screws 157.

The numeral 154 denotes a boss that extends downwardly from the lower face of the top of the gear housing 144, as shown particularly by FIG. 33. That boss is vertically directed and is drilled to accommodate a bushing 156. The top of that bushing extends above the top of housing 144.

The gear housing 144 is provided with a ledge 158 that is at the level of the top of that housing; and that ledge projects outwardly beyond one of the side walls of that gear housing. Part of the front edge of the ledge 158 is plane and the rest is concave, as shown by FIG. 32. The ledge 158 has tapped holes 159 and 160 through it, has a stud 162 extending upwardly from it, has a third threaded hole 164 through it, has an arcuate slot 166 in it, has a fourth threaded hole 168, and has two small sockets 169 adjacent the hole 168. Depending down-

wardly from the forward edge of the ledge 158 is a partially plane, partially arcuate, vertically-directed strut 170 that merges into the one of the two said walls of the gear housing 144; and the arcuate slot 166 in ledge 158 also extends into the upper part of that one wall. A vertically-directed recess 172 is formed in the strut 170 adjacent the outermost edge of that strut. That recess accommodates an L-shaped slide fastener 174 which has a U-shaped notch 176 at the upper end thereof. That L-shaped slide fastener also has an elongated vertical slot 178 intermediate the top and bottom thereof. A fastener 180, such as a rivet, extends through the strut 170 and through the slot 178 in the L-shaped fastener 174. The head of the fastener 180 overlies those portions of the L-shaped fastener which define the slot 178 and thereby prevents separation of that slide fastener from the strut 170. A spiral spring 182 is disposed between the head of the fastener 180 and the rear face of the L-shaped slide fastener 174; and that spring urges the forward face of that slide fastener into intimate engagement with the recess 172 in the strut 170. The force exerted by the spring 182 is great enough to prevent accidental shifting of the L-shaped fastener 174 relative to the recess 172, but that force is small enough to permit that fastener to be shifted relative to that recess, whenever such shifting is desired.

The numeral 184 denotes a ledge which is at the level of the top of the gear housing 144 and which projects outwardly beyond the opposite side wall of that housing. Part of the front edge of the ledge 184 is plane and the rest is concave, as shown by FIG. 32. A partially plane, partially arcuate, vertically-directed strut 186, comparable to the strut 170, is provided at the forward edge of the ledge 184; and that strut merges with the adjacent side wall of the gear housing 144. The strut 186 has a recess 188 which is similar to the recess 172; and that recess accommodates a slide fastener, not shown, identical to the slide fastener 174. This second slide fastener is mounted in the manner in which the slide fastener 174 is mounted. Each of the struts 170 and 186 has an opening to receive the fastener 180 and an opening 189 above the level of the fastener 180.

The ledge 184 is provided with four tapped openings 190, 192, 194 and 196, is provided with a boss 198 extending upwardly from it, and is provided with a second boss 202 extending upwardly from it. The boss 198 has an opening 200 through it and the boss 202 has an opening 204 through it; and those openings have the same diameter. A triangular web 206 extends upwardly from the ledge 184 and abuts the boss 202; and a second triangular web 208 extends upwardly from that ledge and abuts that boss. The triangular webs 206 and 208 are at right angles to each other, as shown particularly by FIG. 4. A connecting web 210 abuts and extends between the bosses 198 and 202.

As shown particularly by FIGS. 2, 3 and 13, the numeral 212 denotes a floor for the gear housing 144. That floor has elongated ribs on the top thereof, and a boss 214 is disposed between those ribs and extends upwardly from the upper surface of that floor. Abutments 213 are provided on the floor 212 at the opposite ends of the ribs, and those abutments fit within and are confined by recesses 215 in the inner faces of the said two walls of the gear housing 144. Those abutments also have threaded openings in which the screws 157 can seat after they pass through the said two walls of the gear housing. The boss 214 is drilled to accommodate a bushing 217, and that bushing will be precisely aligned with the bushing 156 in the boss 154 at the top of the housing 144.

One of the ribs on the floor 212 can be drilled and tapped to receive fasteners 219 that can hold a switch 216 in abutting relation with that rib. That switch has a springy actuator 218 which extends upwardly from it; and when that actuator is moved downwardly it will open the switch 216. Some purchasers of the cup dispenser

provided by the present invention want that cup dispenser to be equipped with the switch 216, but other purchasers of that cup dispenser want the work of the switch 216 to be done by one of the switches in the cam housing 336 attached to the gear housing 144. The cup dispensers supplied to this latter group of purchasers will not be equipped with a switch 216.

The numeral 220 denotes a horizontally-directed arm which carries a vertically-directed, downwardly-depend-
10 ing pin 222; and a roller 224 is rotatably supported at the lower end of that pin. The arm 220 has an upwardly-extending hub 226; and a rounded protuberance 228 extends upwardly from the upper face of that hub. The hub 226 is telescoped upwardly over and is carried by
15 the lower end of the shaft 230 shown in FIG. 20; and that shaft is journaled in the bushings 156 and 217. The shaft 230 has a groove, not shown, adjacent the lower end thereof, and that groove receives a C-washer 232. A helical compression spring 234 surrounds the lower end of the shaft 230, and that spring is disposed between
20 the lower face of the arm 220 and the upper face of the C-washer 232. That spring biases the arm 220 and its hub 226 upwardly relative to the shaft 230 and into engagement with a pin 236 that is held within a radially-
25 directed opening in that shaft. The pin 236 overlies the upper face of the hub 226 and prevents unlimited upward movement of that hub 226; and that pin will normally engage the rounded protuberance 228 on the hub 226 and act through that protuberance to rotate the arm
30 220. However, in the event that arm becomes jammed and held against rotation, the pin 236 will act upon the rounded protuberance 228 and force the hub 226 and the arm 220 to move downwardly and permit the pin 236 to pass by. This is a safety feature which prevents
35 serious injury to the cup dispenser in the event the arm 220 becomes jammed and held against rotation.

As indicated particularly by FIG. 3, the roller 224 has its lower edge disposed below the level of the upper edge of the upstanding cam surface 134 on the closure
40 130. Furthermore, the arm 220 is dimensioned so it places the roller 224 in engagement with that cam surface when that closure is in its right-hand position, as shown by FIG. 20. Counterclockwise rotation of the shaft 230 will cause that roller to engage and roll along the concave rear face of the cam surface 134, thereby forcing the closure 130 to move to its left-hand position, shown by dotted lines in FIG. 20. The position which the roller 224 occupies when it first engages the cam surface 134 is shown by dotted lines at the right-hand side of FIG.
45 20, and the position which that roller occupies before it moves out of engagement with the bent end 135 of that cam surface is shown by dotted lines at the center of FIG. 20. As the roller 224 moves from that right-hand position to that left-hand position, it will move the closure
50 130 from its right-hand position to its left-hand position. If the roller 224 stops in the left-hand position shown by FIG. 20, it will be in engagement with the convex bent end 135 of the cam surface 134, and it will hold the closure 130 in position over the opening 104, thereby
55 completely preventing the passage of a cup downwardly through that opening and also completely preventing the movement of a hand upwardly through that opening. Further counterclockwise rotation of the shaft 230 will move the roller 224 beyond the end 135 of the cam sur-
60 face 134 and thereby permit the spring 138 to move the closure to its right-hand position. That spring is strong enough to provide immediate movement of that closure to its right-hand position. Thereafter, the closure 130 will remain in its right-hand position until further counterclockwise rotation of the shaft 230 again moves the roller 224 into engagement with the rear face of the cam surface 134.

The numeral 238 denotes a crown gear which is mounted on the shaft 230 intermediate the top of gear housing 144 and the floor 212 of that gear housing. That gear

has an upper set of teeth and a lower set of teeth; and the upper set of teeth has a smaller diameter than does the lower set of teeth. Projections 240 extend downwardly from the bottom face of the gear 238, and those projections can engage and be driven by a pin 242 that is carried by, and extends radially outwardly from, the shaft 230. The pin 242 and the projections 240 provide an easily made connection between the shaft 230 and the gear 238. A projection 244 extends downwardly from the lower face of the lower set of teeth on the gear 238; and that projection selectively engages and presses down the actuator 218 of the switch 216. In those instances where the switch 216 is not used, the projection 244 is unnecessary.

The numeral 246 generally denotes a cam which has a hub 248 that telescopes downwardly over the upper end of the bushing 156. The inner diameter of hub 248 is large enough to enable the cam 246 to rotate freely relative to the bushing 156, and thus relative to the shaft 230. An arcuate rise 250 is provided on the cam 246, and that rise has an angular extent of about ninety degrees. A horizontal web 252 extends outwardly from the hub 248; and part of that web extends to the rise 250, as shown particularly by FIGS. 28 and 33. The web 252 has an angular extent of about one hundred and eighty degrees, as shown particularly by FIG. 28; and that web is strengthened by two vertical webs 254 that extend between the hub 248 and the rise 250. A vertically-directed opening 256 is provided in the horizontal web 252, adjacent the trailing edge of that web, and a second vertically-directed opening 258 is provided in that web. The openings 256 and 258 selectively receive a pin 260; and those openings are preferably threaded and that pin preferably has a threaded shank.

There is a very small difference in elevation between the upper face of the bushing 156 and the upper face of the hub 248 of cam 246, and that difference in elevation provides clearance between the upper face of that hub and a washer 262 that encircles the shaft 230 and that rests upon the upper end of the bushing 156, as shown particularly by FIG. 33. Consequently, the cam 246 is freed of the weight of washer 262 and of the weight of disc 264 that is carried by the shaft 230.

The disc 264 has a hub that is secured to the upper end of shaft 230, and that hub can rest upon the washer 262; that washer supporting the downwardly-directed end thrust on the shaft 230. The disc 264 has a D-shaped recess 266 in the top thereof to reduce its mass, and it has an outwardly extending ledge 270 of reduced thickness, as shown particularly by FIG. 16. That ledge has a vertically-directed opening 268 through it, and that opening receives a headed pin 272. The lower end of the shank of the pin 272 has a groove in it, and that groove receives a C-washer 274. The opening 268 is spaced from the axis of shaft 230 a distance comparable to the spacing between that axis and the rise 250 on cam 246; and hence the lower end of the pin 272 can engage and be raised by that rise. The bottom of that pin is smoothly rounded to eliminate any sharp edges that might cut or abrade the surface of rise 250. A recess 276 is provided in the upper part of the disc 264 adjacent the head of the pin 272, as shown by FIG. 14; and that recess permits free vertical movement of the head of that pin and also enables that pin to serve as the driving element of a Geneva gear. A pin 278 is secured to, and extends upwardly from, the disc 264; and that pin is spaced circumferentially from the pin 272.

The numeral 280 denotes a pin that is seated in the hole 196 of the ledge 184 on gear housing 144; and that pin rotatably supports an S-shaped lever 282. A C-washer 283 engages a groove at the upper end of the pin 280 and thereby holds the lever 282 in assembled relation with that pin. One arm of the lever 282 can rotate into abutting engagement with the boss 198, as indicated by

dotted lines in FIG. 28, and that lever will normally be in that dotted-line position. An ear 284 is formed on the lever 282, intermediate the two arms thereof, and that ear receives one end of a spring 286 which is bent around the pin 280. The other end of that spring abuts the boss 198; and that spring biases the lever 282 for rotation in the clockwise direction from the solid-line position to the dotted-line position of FIG. 28. However, that spring will yield to permit that lever to be rotated to its solid-line position. The lever 282 has a hub 288 which extends downwardly and bears against the flange 184, and that hub spaces the body of that lever above the surface of that ledge. A pin 292 is secured to, and extends upwardly from, the S-shaped lever 282, and that pin also is intermediate the two arms of that lever. A second pin 293 extends downwardly from the lever 282, and that pin rotatably supports a roller 290. Intermediate the pin 293 and the other arm of the lever 282 are two bends; and those bends raise that other arm above the level of the rest of the lever 282, as shown by FIG. 13. The tip of that other arm is denoted by the numeral 295, and that tip constitutes a feeler.

The numeral 294 denotes a connecting rod which has openings at the opposite ends thereof; and one of those openings telescopes downwardly over the pin 292 carried by the lever 282 while the other of those openings overlies the web 252 of cam 246 and receives the pin 260. This connecting rod interrelates the lever 282 with the cam 246, and it causes the cam 246 to rotate in the clockwise direction whenever the lever 282 rotates in the counterclockwise direction. The lever 282 and the cam 246 are normally held, by the spring 286, in the positions shown by dotted lines in FIG. 28; but that spring will yield to permit that lever and that cam to be moved to the solid-line positions of FIG. 28.

The numeral 296 denotes an L-shaped cantilever bracket that is supported by the upper face of the ledge 158 on gear housing 144; and aligning pins, not shown, on the bottom of that bracket extend downwardly into sockets 169 in the ledge 158. A bolt 298 extends downwardly through an opening in the foot of that bracket and seats in a tapped opening 168 in the ledge 158. The bracket 296 carries a pivot 300, and that pivot is shown as a screw that seats in the top of that bracket. A hook-like stud 302 extends upwardly from the upper surface of the bracket 296, and that stud is disposed to the right of the pivot 300, as that stud and pivot are viewed in FIG. 28.

The pivot 300 rotatably supports a lever which is generally denoted by the numeral 304. That lever has a horizontal portion 306 which rests upon, but is movable relative to, the upper face of the bracket 296, and that horizontal portion has an opening which receives the pivot 300. The horizontal portion 306 is notched to accommodate the stud 302, and the notch of portion 306 abuts that stud to limit rotation of lever 304 in the counterclockwise direction. An ear 308 extends upwardly from the horizontal portion 306 of lever 304, and that ear is adjacent that edge of horizontal portion 306 which is remote from the stud 302. A downwardly inclined portion 310 of lever 304 supports a second horizontal portion 312; and that second horizontal portion has a pin 311 extending downwardly from it to rotatably support a roller 314. That second horizontal portion also has a horizontally-directed extension 316, welded or otherwise secured to it; and that extension has a downwardly depending apron 318. The leading edge of that apron is bent inwardly to provide an inclined pressure-applying face, as shown by FIGS. 1 and 28. The second horizontal portion 312 of lever 304 also has a narrow portion 315 that is bent vertically downwardly and is then bent horizontally. The vertical part of the narrow portion 315 extends downwardly through the arcuate slot 166 in the ledge 158 and in the said one wall of gear housing 144; and the tip 317 of the horizontal part of that narrow portion

extends beyond the gear housing 144 to constitute a feeler. The numeral 322 denotes a spring which is bent around the pivot 309, and which has one end thereof held by the ear 308 and has the other end thereof held by the stud 302. That spring biases the lever 304 for rotation in the counterclockwise direction, but it can yield to permit that lever to be rotated in the clockwise direction.

The numeral 324 denotes a switch-supporting bracket which is generally L-shaped in plan, and which underlies and partially overlies a switch 330. In partially overlying the switch 330 that bracket protects and conceals the terminals of that switch. The bracket 324 has an opening which telescopes over the stud 162 on the ledge 158 of gear housing 144, and that opening and that stud enable that bracket to be rotated relative to the ledge 158. In addition, the bracket 324 has an arcuate slot 326 which is concentric with the opening that telescopes over the stud 162. A screw 328 extends downwardly through the slot 326 and seats in the opening 160 in the ledge 158; and tightening of that screw holds the bracket 324 against rotation relative to the ledge 158. Fasteners 332 secure the switch 330 to the bracket 324, but those fasteners stop short of the ledge 158 so they can not prevent rotation of the bracket 324 relative to that ledge. If desired, the top surface of that ledge can be recessed to make certain that the lower ends of those fasteners do not engage that ledge. The switch 330 has a button 334 which extends outwardly from it, and that button is in register with the apron 318 on the extension 316 carried by the horizontal portion 312 of lever 304. The exact position of that button relative to the apron 318 is determined by the setting of the bracket 324; and that setting is effected by loosening the screw 328, rotating the bracket 324 about the stud 162 until the button 324 is in the path of the inclined leading edge of the apron 318, and then tightening the screw 328. When the feeler 317 of lever 304 is in the dotted-line position of FIG. 28, the apron 318 will be in engagement with the button 334 of switch 330 and will be holding that button in switch-closing position; and when the feeler 317 is in the solid-line position of FIG. 28, the apron 318 will be out of engagement with the button 334, and the switch 330 will be able to open the circuit.

The numeral 336 generally denotes a housing in which cams and switches are mounted. That housing is preferably made rectangular in configuration, and it is provided with end plates 340 and 342. The end plate 340 has three bosses 338 thereon and those bosses are suitably drilled. The sizes and locations of the bosses 338 are comparable to the sizes and locations of the bosses 150 on the gear housing 144. As a result, fasteners can extend through the bosses 150 and 338 and rigidly secure the cam housing 336 to the gear housing 144. A cam housing 384, identical to the cam housing 336, is also mounted on the housing 144.

As indicated particularly by FIG. 29, the end plate 340 of gear housing 336 has a sleeve 344 extending outwardly from it; and that sleeve is drilled to accommodate an elongated shaft 348. A crown gear 350 is secured to the shaft 348 by a set screw 352, and that gear meshes with the lowermost set of teeth on the crown gear 238 carried by the shaft 230. The other end of the shaft 348 extends through the cam housing 336 and is supported by a boss 346 on the end plate 342; the boss 346 having a shaft-receiving opening through it. As indicated particularly by FIG. 29, the shaft 348 can extend outwardly beyond the end plate 342 of cam housing 336.

A washer 354 is telescoped over the shaft 348 and is disposed adjacent the inner end of sleeve 344; and a springy washer 355 is telescoped over that shaft and is disposed adjacent the washer 354. A collar 356 is telescoped over the shaft 348 and is disposed adjacent the springy washer 355; and a set screw 358 locks that collar in position on the shaft 348. The springy washer 355 presses the washer 354 against the inner end of sleeve

344 and also holds the gear 350 against the outer end of that sleeve, and thereby prevents end play of the shaft 348.

A sleeve 360 is provided with reduced diameter portions 362 at the opposite ends thereof, and that sleeve is locked on the shaft 348 by a set screw 364. An axially-extending slot 366 is formed in the exterior of the sleeve 360; and that slot is made deep enough to extend radially inwardly of the reduced diameter portions 362. The numeral 368 denotes washers which have inner diameters that are larger than the diameters of the reduced diameter portions 362 but are smaller than the outer diameter of sleeve 360. Each of those washers has a projection 369 extending inwardly from the inner periphery thereof, and that projection is dimensioned to fit within and be held by the axially-extending slot 366. The interaction between the projections 369 and that slot prevents relative rotation of the washers 368 and sleeve 360. The numeral 370 denotes a cam which has a high dwell of one hundred and eighty degrees and has a low dwell of the same length; and the numeral 372 denotes a cam which is identical with the cam 370. Each of the cams 370 and 372 has a central opening which is larger than either of the reduced diameter portions 362 but is smaller than the outer diameter of sleeve 360. In addition, each of the cams 370 and 372 has axially-extending holes 374 to receive a spanner wrench. Furthermore, each of the cams 370 and 372 has graduations and numerals thereon, as shown particularly by FIG. 30; and those graduations divide the angular extent of each of those cams into three hundred and sixty degrees. The graduation corresponding to zero degrees is aligned with the rise between the low dwell and the high dwell of the cam. As shown by FIGS. 30 and 31, the rises and falls of the cams 370 and 372 are radially-directed and hence are quite abrupt.

Each of the reduced diameter portions 362 of the sleeve 360 can accommodate a cam 370 plus a cam 372; and the shaft 348 and the housing 336 are made long enough to accommodate two sleeves 360. Hence the cam housing 336 encloses four composite cams, each of which includes a cam 370 and a cam 372. If desired, the shaft 348 and the housing 336 could be made long enough to accommodate three, four or even five sleeves 360.

In mounting the cams 370 and 372 on a sleeve 360, a washer 368 is telescoped over one of the reduced diameter portions 362 and then pressed against the shoulder between that reduced diameter portion and the central portion of the sleeve 360. Thereafter, a cam 370 is telescoped over that reduced diameter portion and is pressed against the washer 368. A second washer 368 is then set against the outermost face of the cam 370, and a cam 372 is set against the outermost face of the second washer 368. Thereupon, a third washer 368 is set against the outermost face of the cam 372, and an internally toothed, star washer 378 is telescoped over the reduced diameter portion 362 and is pressed tightly against the outermost washer 368. The teeth of the star washer 378 will engage the reduced diameter portion 362 and prevent accidental separation of the cams 370 and 372 and of the washers 368 from the sleeve 360; and the washers 368 will apply sufficient frictional forces to the cams 370 and 372 to prevent accidental rotation of either of those cams relative to each other or to the sleeve 360. However, those washers will permit rotation of those cams relative to each other and relative to that sleeve whenever spanner wrenches are seated in the openings 374 and sufficient rotative forces are applied to those spanner wrenches. By properly setting the cams 370 and 372 relative to each other, a high dwell of from one hundred and eighty degrees to three hundred and sixty degrees can be attained. Furthermore, by rotating the cams 370 and 372 relative to the sleeve 360, the desired angular position of the high dwell can be set. To facilitate the proper setting of the cams 370 and 372, those cams are mounted with their graduated, numeral-bearing faces exposed. Furthermore, each of the washers 368 is formed with a radially-extending in-

dexing edge 371, and that edge is in register with the slot 366. As a result, to attain a low dwell that is centered on the slot 366 and that has an angular extent of sixty degrees, it is only necessary to set the cam 370 so its thirty degree graduation is at the indexing edge 371 of the adjacent washer 368 and to set the cam 372 so its thirty degree graduation is at the indexing edge 371 of the adjacent washer 368. To facilitate error-free reading and setting of the cams 370 and 372, the portions of washers 368 adjacent the indexing edges 371 are set to expose all graduations between those edges and the zero graduations; and this means that the washer 368 at the exposed face of cam 370 will be rotated one hundred and eighty degrees, about a radius of shaft 348, from the position occupied by the washer 368 at the exposed face of cam 372.

The numeral 390 denotes a bracket which is generally rectangular in configuration, which has sides that are parallel to and abut two of the inner faces of the cam housing 336, and which has inwardly extending flanges to define a generally rectangular opening. That bracket also has a foot with tapped openings therethrough to receive fasteners 392 that extend through openings in the end plate 340 of the cam housing 336 and seat in those tapped openings. The bracket 390 is set within the cam housing 336 adjacent an opening 394, and that opening permits electrical leads to extend into that cam housing and to be connected to switches mounted on that bracket. Those switches are denoted by the numeral 396, and they are standard switches made by the Cherry Electrical Products Corporation. The terminals of those switches are denoted by the numerals 398, 400 and 402; and those terminals receive electrical leads, not shown, which are connected to various electrically-controlled components of the coin-operated drink-vending machine. If desired, one of the switches 396 can be used to perform the function of the switch 216 mounted in the gear housing 144; and where that is done, the switch 216 can be dispensed with and the crown gear 238 can be made without the downwardly depending, switch-actuating projection 244. Each of the switches 396 is provided with a switch arm 404 that is raised by the rises and is held by the high dwells of the composite cams on the shaft 348; those switch arms rotating relative to the pivot brackets 406 of those switches.

The numeral 410 denotes the housing of a commercially available gear motor; and that housing has three drilled and tapped bosses 412. That housing also has a sleeve 414 which is drilled and bushed to support output shaft 416 of the motor. In the embodiment shown by FIGS. 1, 2 and 4, a pin 418 is carried by shaft 416, and that pin engages a notch in a connector 420. That connector is fixedly mounted on shaft 348; and pin 418 coacts with that connector to transmit rotative forces from the motor shaft 416 to shaft 348 while compensating for any slight misalignments of those shafts. The bosses 338 on end plate 342 of cam housing 336 and the bosses 412 on gear motor housing 410 are spaced apart by sleeves 422; and bolts extend through those sleeves and seat in the drilled and tapped bosses 412 to hold gear motor housing 410 rigid relative to cam housing 336.

The numeral 382 denotes a shaft rotatably mounted in the cam housing 384, and that shaft supports a crown gear 380. That gear engages and is driven by the upper set of teeth on the crown gear 238.

The numeral 430 denotes a cylindrical pivot that is preferably made hollow to reduce its weight. That pivot has a reduced diameter lower portion which can telescope into the opening 200 of boss 198 or into the opening 204 of boss 202 on ledge 184 of gear housing 144. The shoulder defined by that reduced diameter portion will rest upon and be supported by the upper face of boss 198 or 202. A set screw, not shown, in boss 198 or boss 202 will fixedly hold that pivot.

The driven element 432 of the Geneva gear, used in the cup dispenser, has a central opening that is larger than

the outer diameter of the pivot 430, and that driven element has a downwardly extending flange that rests upon the upper face of the boss 198 in which the pivot 430 is mounted. That driven element also has a short upwardly extending flange, and both flanges abut and define the central opening. That central opening is sufficiently large to permit free rotation of the element 432 relative to the pivot 430. The driven element 432 has six radially-directed slots extending inwardly from the periphery thereof because it is used with a stack-carrying turret intended to support and carry six stacks of cups; and each of those slots is dimensioned to accommodate the upper part of the shank of the headed pin 272 carried by the ledge 270 of disc 264. The portions of the periphery of the driven element 432 that are intermediate the six slots are concave, and the radii of those intermediate portions are slightly larger than the radius of the disc 264. The driven element 432 also has six vertically-directed holes 434 formed in it, and those holes are located between the slots of the driven element 432. The six holes are located on three diameters of that driven element, and they are all equidistant from the geometric center of that driven element. As indicated by FIG. 5, the holes 434 are frustoconical in vertical section and the apex angle is less than forty-five degrees.

The numeral 438 denotes a circular support which has a low, upwardly directed peripheral flange. That support also has a downwardly directed annular flange 440 which defines a discharge opening 441 for cups; and that flange and that opening are spaced inwardly from the periphery of the support 438. A number of concentric arcuate ridges 442 are formed at the upper surface of the support 438, and those ridges minimize the frictional forces between that support and the bottoms of cups resting upon that support. An opening 444 is provided at the center of the support 438, and that opening is made large enough to telescope loosely over the upper end of the cylindrical pivot 430.

Struts 446, 448, 450 and 452 are provided to carry the support 438, and those struts extend between that support and the ledges 158 and 184. Each of those struts has a horizontally-directed lower portion with an opening to receive a fastener 454, each has a horizontally-directed upper portion, and each has an inclined intermediate portion. The upper portions of the struts 446, 448, 450 and 452 have openings to receive bolt-like fasteners, not shown, that depend downwardly from the support 438. The strut 446 is set adjacent the hole 194 in ledge 184, the strut 448 is set adjacent the hole 192 in that ledge, the strut 450 is set adjacent the hole 190 in that same ledge, and the strut 452 is set adjacent the hole 164 in the ledge 158. Fasteners 454, in the form of screws, extend through the openings in the horizontally-directed lower portions of those struts and seat in the holes 194, 192, 190 and 164. Cylindrical, partially knurled nuts 456 telescope over and engage the shanks of the fasteners which depend downwardly from the support 438 and which extend through the openings in the horizontally-directed upper surfaces of the struts 446, 448, 450 and 452. Nuts 458 are telescoped over the shanks of the bolt-like fasteners carried by the support 438 after those shanks are telescoped downwardly through the support 438 and before those fasteners pass through the horizontally-directed upper portions of the struts; and those nuts fixedly lock those fasteners in position on the support 438.

The opening 441 defined by the flange 440 is adjacent the ends of the upstanding ridges 442 on the support 438. This means that the ridges 442 are able to minimize the frictional forces between the bottoms of the cups and the upper face of the support 438 as those cups are moved around to the discharge opening 441.

The numeral 460 denotes a hub for the stack-carrying turret of the cup dispenser; and that hub has a tapered opening through it, with its smallest-diameter portion larger than the outer diameter of the pivot 430. The

largest-diameter portion of the tapered opening in hub 460 is larger than the upwardly extending flange on the driven element 432 of the Geneva gear; and, consequently, the hub 460 can be telescoped downwardly over the pivot 430 and can also have its lower end telescoped over the said flange at the top of the driven element 432 of the Geneva gear. Two downwardly-extending bosses 464 are provided at the bottom face of the hub 460, and those bosses extend into two of the holes 434 in the driven element 432. Those portions of the driven element 432 which define the holes 434 coat with the bosses 464 to transmit rotational forces from that driven element to the hub 460; but if the turret becomes jammed, the frusto-conical walls of the holes 434 will act as inclined planes and raise the bosses 464 up out of those holes. Those bosses will then drop into the next pair of holes 434 and, if the cause of the jam has been removed, those bosses will rotate with the driven element. However, if the turret is still jammed, the bosses 464 will be raised up out of those holes and all successively presented holes until the jam clears or the power is turned off. The frusto-conical vertical section of the holes 434 thus coacts with the bosses 464 to prevent injury if the turret becomes jammed.

A flange 462 is provided intermediate the top and bottom of the hub 460, and that flange has a number of holes in it. Those holes are in register with corresponding holes in a polygonal plate 468 which is provided with downwardly-extending flanges at each of the edges thereof; and fasteners 478 extend through the holes in flange 462 and in plate 468 to hold them in assembled relation. The downwardly extending flanges on plate 468 are welded or otherwise secured to the lower edges of vertically-directed bent plates 470. Each of those bent plates has a panel which is as wide as one of the faces of the polygonal plate 468, and it is the lower edges of those panels to which the flanges on plate 468 are welded. Each of the bent plates 470 has a securing flange adjacent one edge of the said panel, has a second panel which extends radially outwardly from the polygonal plate 468 and which is contiguous with the other edge of the first said panel, has a third panel which inclines forwardly and ahead of the second panel, and has a second securing flange contiguous with the outer edge of the third panel. The third panel and the second panel coat to define a shallow V; and the V's of the various bent plates 470 coat to guide the stacks of cups into registry with the discharge opening 441 as those bent plates move those stacks of cups toward that opening.

The arrangement of the bent plates is shown particularly by FIG. 6; and those plates are maintained in that arrangement by an upper ring 472 and a lower ring 474. Those rings are suitably secured to the second securing flanges of the bent plates 470, as by welding. The ring 474 is dimensioned so it can telescope within the upwardly-directed flange on the support 438; and the ring 472 is about the same size as the ring 474. A transparent sleeve 476 telescopes over, and is secured to, the rings 472 and 474. The resulting turret protects the stacks of cups and also gives a visible indication of the number of cups therein. The turret can be handled as a unit, and it is easily lifted off of the pivot 430. Also, that turret can easily be telescoped onto that pivot and set so the bosses 464 are in register with, and telescope down into, the openings 434 in the driven element 432. A cover 480, which is provided with a short, downwardly-extending peripheral flange, is provided for the turret; and the inner diameter of that cover is larger than the outer diameter of the ring 472 at the top of the turret. Although the transparent sleeve 476 is telescoped over the rings 472 and 474 of the turret, its upper and lower ends terminate short of the flanges on the cover 480 and on the support 438.

To insert cups within the turret, it is only necessary to remove the cover 480 and to fill the various spaces

defined by the bent plates 470. As the cups are telescoped down into those spaces, the cups will, with the exception of the space which is in register with the discharge opening 441, soon come to rest on the ridge 442. Cups introduced into the space in register with that discharge opening will be supported by the fingers of the cup dispenser.

The numeral 482 denotes a yoke which has a cylindrical base that can either fit within the opening 294 of the boss 202 or can fit within the opening 200 of the boss 198. That base will be held against rotation, and against vertical movement, relative to the boss in which it is mounted by a set screw, not shown, in the wall of that boss. A cylindrical, vertically-directed recess 484 is provided in the base of the yoke 482, and a headed pin 486 has the lower end of the shank thereof telescoped down into that recess. A helical compression spring 488 is disposed within the recess 484, and it bears against the bottom face of the shank of the pin 486. The head of the pin 486 bears against the flat under-face of the right-hand end of a lever 492; and that lever is rotatably secured to the yoke 482 by a pivot 490. The spring 488 acts through the pin 486 to bias the lever 492 to the generally horizontal position shown by FIGS. 1 and 15. The left-hand end of the lever 492 is provided with a pin 496 which depends downwardly and with a cam 498 that extends upwardly. Intermediate the pin 496 and the right-hand end of lever 492 is a downwardly depending cam 499; and intermediate the cam 498 and that right-hand end is an upwardly extending pin 494. The cams 498 and 499 are inclined to the axis of the lever 492, as shown particularly by FIG. 14, and the leading edges of those cams are inclined to the horizontal. The lever 492 will have pin 496 and cam 499 at the lower face thereof whenever the base of yoke 482 is set in opening 294 of boss 202; but that lever will be rotated one hundred and eighty degrees about pivot 490 to place pin 494 and cam 498 at the lower face thereof whenever the base of yoke 482 is set in opening 200 of boss 198.

The pin 496 is spaced from cam 499 a distance equal to the distance between two slots in driven element 432; and, consequently, pin 496 and cam 499 can, and are intended to, simultaneously lodge in two of the slots of driven element 432. The cam 498 and pin 494 are spaced apart a distance equal to the distance between two slots in the driven element of FIG. 17, and, consequently, that cam and pin can, and are intended to, simultaneously lodge in two of the slots of driven element 700. When so lodged, the cams and pins will effectively prevent rotation of the driven elements. However, those cams and pins can be raised out of the slots in the driven elements to permit rotation of those driven elements by the driving elements of the Geneva gear. The cam 499 is set in the path of headed pin 272 carried by ledge 270 on disc 264; and when that pin is raised up against cam 499 by the rise 250 of cam 246, it will cause the lever 492 to rotate in the clockwise direction and raise pin 496 and cam 499 out of the slots of driven element 432. A similar pin is provided on the disc of FIG. 17 to engage and raise cam 498. Consequently, while lever 492 normally holds the driven element of the Geneva gear stationary, that lever can be rotated to free that driven element. The pin 496 will respond to forces applied to it by the sides of a slot in driven element 432 to successfully resist the forces which the sides of the succeeding slot apply to the cam 499 to tend to rotate the lever 492 and the yoke 482 in the counterclockwise direction.

Cup-Separating Head and Associated Components

The numeral 500 generally denotes a cup-separating head that is an integral part of the cup dispenser of FIGS. 1 and 2. That head has a generally cylindrical body 502 and has an inwardly-directed flange 504 at the top of that body. Four arcuate abutments 506 extend vertically downwardly from the inner edge of the flange 504, and

those abutments are spaced apart equal distances. A narrow and shallow arcuate ridge 505 projects upwardly from the top of the body 502 at one edge of that body, as shown particularly by FIG. 37; and that ridge has an angular extent of approximately ninety degrees. Two vertically-extending abutments 508 are provided at the exterior of the body 502, and those abutments are adjacent the ends of the ridge 505. Each of those abutments has a flat face which can engage and abut the plane portion of one or the other of the vertically extending struts 170 and 186 on the gear housing 144. The portion of the generally cylindrical body 502 which is intermediate the abutments 508 is convex and is complementary to the concave portion of the top of the gear housing 144 and to the concave parts of the front edges of the ledges 153 and 184. Cylindrical bosses 510 are provided at the front of the body 502; and the lower ends of those bosses, as well as the lower ends of the abutments 508, are provided with drilled and tapped holes. Short cylindrical projections 509 are provided at the tops of the abutments 508, and similar cylindrical projections 511 are provided at the tops of the bosses 510. Drilled and tapped openings, not shown, extend vertically downward through projections 509 and 511 and into abutments 508 and bosses 510, respectively. Pins 512, with grooves adjacent the outer ends thereof, extend horizontally outwardly from the abutments 508; and those pins extend through the openings 189 in the struts 170 and 186. The grooves in those pins are engaged and held by those portions of the upper ends of L-shaped fasteners 174 which define the notches 176. As a result, in assembling the cup-separating head 500 with the gear housing 144, it is only necessary to telescope the grooved pins 512 through the openings 189 in the struts 170 and 186 on that housing and then move the slide fasteners 174 upwardly until the slots 176 in the slide fasteners telescope over the grooves in the pins 512. Two cylindrical studs 514 project horizontally outwardly from that part of the front of body 502 which is intermediate the bosses 510. Those studs have drilled and tapped openings, not shown, in the outer ends thereof.

The numeral 516 denotes two triangular stops that project upwardly from the upper face of the flange 504; and those stops are at opposite ends of a diameter of the body 502. The vertical faces of those stops are generally in alignment with the edges of two of the abutments 508. The flange 504 is provided with eight vertically-directed holes 520 which are counterbored to provide conical recesses at the tops thereof and to provide cylindrical recesses at the bottoms thereof; and two of those holes are adjacent the vertical faces of the stops 516. The flange 504 is also provided with four vertically-directed holes 522 of uniform diameter, and those holes are spaced apart equal distances. A horizontally-directed slot 524 is provided in the cylindrical wall 502 intermediate the abutments 508, and that slot is formed and dimensioned to accommodate the tip 317 and part of the narrow portion 315 of feeler lever 304. A notch 526 is provided in the cylindrical wall 502 at the lower edge of the front of that wall, and that notch extends upwardly from that lower edge. That notch is generally L-shaped in configuration and it is located between the cylindrical bosses 510. A short, horizontally-directed boss 528 is provided on the cylindrical wall 502 immediately adjacent the notch 526, and that boss has a hole 530 through it.

A short pivot 532 has one end thereof rotatably mounted in the hole 530 of boss 528; and the other end of that pivot is threaded. A shoulder 534 is formed on the pivot 532, and that shoulder is disposed adjacent the outer face of boss 528. A cam 536 and an adjusting lever 538 have openings therethrough that accommodate the outer end of the pivot 532; and a nut 550 is threaded onto the outer end of the pivot 532 and tightened to clamp the cam 536 and the adjusting lever 538 against the shoulder 534, as shown by FIG. 22, thereby preventing movement of that cam relative to that adjust-

ing lever. If desired, a star washer 537 can be disposed between the cam 536 and the adjusting lever 538 to provide even more positive holding of those elements against relative rotation, as shown by FIG. 37. A reference panel or dial 540, of generally semi-circular configuration, has openings 542, 544 and 546 through it. The opening 542 telescopes loosely over the pivot 532 and also telescopes over the nut 550 on that pivot. The openings 544 and 546 accommodate fasteners 554 which extend through those openings and seat in the threaded openings in the studs 514. The dial 540 has graduations and numerals thereon and those graduations subtend an angle of almost one hundred and eighty degrees. The dial is large and the adjusting lever 538 is large, and hence the setting of the lever 538 is not a critical adjustment but is one within the capabilities of most persons. As indicated particularly by FIGS. 22 and 37, the outer end of the lever 538 is bent forwardly and then inwardly to enable it to serve as a pointer. A knurled nut 552 is provided with a recess that telescopes loosely over the nut 550, and that nut is threaded onto the outer end of the pivot 532. Tightening of the nut 552 clamps the adjusting lever 538 against the rear face of panel 540 and thereby locks the cam 536 against rotation. Loosening of the nut 552 permits lever 538 to be rotated to rotate cam 526, and that rotation will enable that cam to apply a side thrust to a projection on a positioning ring mounted within the cup-separating head 500.

As shown particularly by FIG. 3, a sleeve 558 has a radially-extending flange which fits in the counterbored bottom of one of the holes 520 in the flange 504 of body 500. The upper end of that sleeve can be riveted over to fit the conical counterbore at the top of that opening. The riveting over of the upper end of the sleeve coacts with the flange on that sleeve to fixedly lock that sleeve in that opening. Two such sleeves are provided for the cup-separating head 500, and those sleeves are set in those holes 520 which are adjacent the vertical faces of the stops 516. A generally U-shaped, upper, cup-separating finger is denoted by the numeral 560, and it has a vertically-directed opening 562 through it; and that opening is dimensioned to permit the finger 560 to be telescoped upwardly over the lower end of the sleeve 558. A groove is provided in the exterior of the sleeve 558 adjacent the bottom of that sleeve, and that groove receives a C-washer 559 which underlies the finger 560 and maintains it in assembled relation with sleeve 558 and also prevents vertical movement of that finger relative to that sleeve. A second vertically-directed opening 564 is provided in the other arm of the finger 560, and the openings 562 and 564 are parallel. A helical spring 568 is telescoped over the upper end of that arm of finger 560 which has the opening 562; and thereafter a washer 556 is staked or otherwise permanently secured to the upper end of that arm. The washer 556 and the closed end of the U-shaped finger 560 prevent accidental separation of the spring 568 from that finger. One end of that spring bears against the other arm of the finger 560 while the other end of that spring bears against the outer face of one of the abutments 508. That spring biases the finger 560 for rotation in the clockwise direction about the sleeve 558, and it biases that finger for rotation toward the abutment which holds the other end of the spring for that finger. When the finger is in engagement with that abutment, it is directed inwardly of the body 500 and is generally radially directed. The spring 568 can, however, yield to permit the finger 560 to be rotated in the counterclockwise direction toward the cylindrical wall 502. A thin, horizontally-directed lip 570 is provided at the bottom of that arm of finger 560 which has the opening 564; and that lip has a vertical dimension which is less than one half the distance between the rims of two stacked cups. The lip 570 is defined by two convex arcs, as shown particularly by FIG. 38; and the longer of those arcs is con-

tric with that arm of finger 560 which has the opening 564.

The numeral 572 denotes a lower cup-separating finger, and that finger has a reduced height portion with a vertically-directed opening 573 therein. The opening 573 has a diameter that is smaller than the diameter of the opening 562 or of the outer diameter of the sleeve 558; and that opening receives the lower end of a pin 579 which is disposed within, but extends downwardly beyond, the sleeve 558. A groove is provided in the pin 579 adjacent the bottom of the finger 572 and a second groove is provided in that pin adjacent the top of the reduced height portion of that finger; and a C-washer 583 is disposed in the lower groove while a C-washer 582 is disposed in the other groove. Those C-washers maintain the finger 572 in assembled relation with the pin 579 and also prevent relative vertical movement of that pin and finger.

The finger 572 has a flat upper face 576 that can abut the bottom of that portion of finger 560 which has the opening 564; and that bottom and that flat face have substantially the same configuration in plan view. A pin 578 extends upwardly from the surface 576, and that pin telescopes up into the opening 564 in the finger 560; and the diameter of that pin is sufficiently smaller than the diameter of the opening 564 to enable the finger 572 to move up and down freely relative to the finger 560. A lip 574, which is similar in configuration to the lip 570 on the finger 560, is also provided on the finger 572. The combined height of the lips 570 and 574 is approximately fifty thousandths of an inch, and this height is less than the spacing between the rims of two stacked cups.

The reduced height portion of the finger 572 accommodates the C-washer 559 and also accommodates the C-washer 562, thereby permitting the surface 576 to abut the bottom face of the finger 560. That surface is biased into abutting relation with that bottom face by a helical compression spring 580 that surrounds the upper end of the pin 579 and has its lower end bearing against the riveted upper end of the sleeve 558. The upper end of the spring 580 bears against the lower face of a C-washer 585 which is held within a groove, not shown, in the upper end of the pin 579. That spring biases the pin 579 upwardly, and thereby biases the finger 572 upwardly toward the bottom face of the finger 560. However, that spring can yield to permit downward movement of the pin 579; and when that pin moves down, it will move the finger 572 down with it. The downward movement of the pin 579 is less than the height of the pin 578, and therefore the upper end of the pin 578 will always remain within the opening 564. This is desirable because it enables rotative forces applied to the finger 560 to cause rotation of finger 572 as well.

The numeral 602 denotes a pin which has a flanged, hollow, large diameter upper end; and the flange of that upper end can be seated in the cylindrical counterbore, while the wall of the hollow portion can be riveted over in the conical counterbore, of one of the holes 520, all as shown by FIG. 11. Two pins 602 are provided for the body 560, and those pins are set in the holes that are equidistant from the holes containing the sleeves 558. The lower ends of the pins are dimensioned to telescope within the openings 562 of fingers 561; and grooves in the lower ends of those pins receive C-washers 604 that hold the fingers 561 in assembled relation with the pins 602, as shown by FIG. 11. The pins 602 and the C-washers 604 prevent vertical movement of the fingers 561 held thereby, but they permit free rotation of those fingers. The fingers 561 are identical to the fingers 560, except for the fact that the openings 562 in fingers 561 are just large enough to accommodate pins 602 whereas the openings 562 in fingers 560 are large enough to accommodate the sleeves 558.

The numeral 584 denotes a pin which has a flanged, 75

hollow, large diameter upper end; and the flange of that upper end can seat in the cylindrical counterbore, while the wall of the hollow portion can be riveted over in the conical counterbore, of one of the holes 520, all as shown by FIG. 12. Four pins 584 are provided for the body 560, and those pins are disposed in holes 520 that alternate with the holes 520 for sleeves 558 and pins 602. The pins 584, are similar to, but longer than, the pins 602.

A helical compression spring 606 is telescoped up over the bottom of each pin 584 and then the opening 588 in the hub 586 of a stack-supporting finger 587 is telescoped up over the lower end of that pin. A C-washer 600 is mounted in a groove adjacent the bottom of pin 584, and that C-washer holds the finger 587 in assembled relation with pin 584 while permitting that finger to move vertically relative to that pin. The spring 606 biases the finger 587 downwardly toward the C-washer 600, but it can yield to permit that finger to be held above, and 20 out of engagement with, that C-washer. In addition to being vertically movable relative to the pin 584, the finger 587 is rotatable relative to that pin.

The stack-supporting finger 587 has a recess, in the upper end of the hub 586 thereof, which is an enlargement of the opening 588; and that recess accommodates the lower end of the helical compression spring 606. The upper end of that spring abuts the flange on the large diameter upper end of the pin 584. The finger 587 also has a smoothly rounded, cylindrical surface 589, and that surface is made hollow to reduce its mass. The hub 586 and the surface 589 are interconnected by a web 591; and both the hub 586 and the surface 589 extend upwardly above the top of that web to provide a generally U-shaped configuration for the upper part of the finger 587. A helical spring 590 is telescoped over the upper part of the hub 586, and one end of that spring bears against the cylindrical surface 589 while the other end of that spring bears against one of the vertically-extending abutments 506. A washer 592 is telescoped over the upper end of the hub 586, and the upper end of that washer is then staked or otherwise permanently secured to that hub to prevent accidental separation of that washer from that hub. The cylindrical surface 589 terminates at a horizontally-directed shoulder 596, and that shoulder has a generally frusto-conical surface 594 depending downwardly therefrom. That surface is concentric with the cylindrical surface 589; and, like the surface 589, it is hollow. The shoulder 596 is deeper than the width of the largest rim on the cups to be dispensed 25 by the cup dispenser, and hence the frusto-conical surface 594 will engage the sides of a cup and keep the rim of that cup from engaging the cylindrical surface 589. The frusto-conical surface 594 has an apex angle that is substantially the same as the apex angle of most commercially available cups that can be used in coin-operated, drink-dispensing vending machines. The frusto-conical surface 594 is biased for rotation in the counterclockwise direction toward an adjacent abutment 506, but it can be rotated in the clockwise direction toward the cylindrical wall 502. The extent of the rotation of the finger 587 is not, however, unlimited; and throughout all of the rotation of that finger, the stud 598 on the rear of the hub 586 will overlie the positioning ring of FIG. 23. As shown by FIGS. 44 and 45, the cylindrical surfaces 589 are not truly cylindrical but, instead, are slightly tapered; being larger at the bottom than at the top.

The numeral 610 denotes an elongated tube which is preferably made of a transparent plastic material. As shown particularly by FIG. 3, a horizontal flange 612 is provided at the top of that tube, and that flange merges smoothly with the wall of that tube. Triangular struts 614 extend between the outer periphery of the tube and the bottom surface of the flange 612 to stiffen and strengthen that tube. Fasteners 616 extend upwardly

through openings in the flange 612 and seat in the drilled and tapped openings in the bottoms of bosses 510 and abutments 506 on the body 500. As indicated by FIG. 21, an arcuate slot 618 is provided in the flange 612, and it is concentric with the tube 610; and that slot has an angular extent comparable to the angular extent of the lower part of the notch 526 in the cylindrical wall 502.

The numeral 620 denotes a cam ring which is disposed within the lower part of the body 500 and which rests upon the flange 612 of the tube 610. That ring is shown particularly by FIG. 25; and it has a protuberance 622 at the exterior of the ring 620, and that protuberance projects into the lower part of the notch 526 in the cylindrical wall 502. That protuberance is drilled and tapped to receive the threaded shank of a set screw 623 which has a knurled head. As shown particularly by FIGS. 2 and 21, the knurled head of set screw 623 extends downwardly below the level of the flange 612 on tube 610; and that head will, therefore, act as a visual indication of the position of the cam 620. Loosening of the set screw 623 will permit rotation of the cam 620 relative to flange 612 and body 500; and tightening of that set screw will lock that cam against rotation relative to that body and that flange. The cam 620 has four low dwells 624, has four shallow inclined rises 626, has four intermediate dwells 628, has four shallow inclined rises 630, and has the top thereof as a high dwell 632. The dwells and rises 624, 626, 628, 630 and 632, in each of the four groups of dwells and rises, are contiguous.

The numeral 634 denotes the positioning ring of FIG. 23, and that ring is disposed within the body 500 and is also disposed above the level of the cam ring 620. The positioning ring 634 has four pins 636 thereon, and those pins are vertically directed. Those pins are spaced apart so they can be placed in register with the four dwells 624, with the four rises 626, with the four dwells 628 or with the four rises 630. Also those pins can be placed in register with plane portions of the top surface of ring 620. The portions of the pins 636 which extend downwardly from the ring 634 are smaller in diameter than are the portions of those pins which extend upwardly from that ring. Adjacent each of the pins 636 is an outwardly extending projection 638, and those projections will closely approach the cylindrical wall 502. Those projections minimize the frictional forces between the positioning ring 634 and the body 500. The cross section of the ring 634 is reduced at two points, as indicated by the numeral 640; and the reduced cross section portions 640 are adjacent the two sleeves 558. The C-washers 559 which fit into the grooves at the bottoms of those sleeves must be large, and they can be so large that they could interfere with the vertical movement of the positioning ring 634 if that ring was not provided with the reduced cross section portions 640. A stud 642 projects radially outwardly from the ring 634, and that stud extends through the upper part of the notch 526 in the cylindrical wall 502, as shown particularly by FIG. 21. That stud will be engaged and moved by the cam 536. The positioning ring 634 rests upon the cam ring 620, and the studs 593 of the fingers 587 rest upon the positioning ring. The springs 690 bias those fingers and the positioning ring downwardly within the head 500, but the pins 636 can be shifted upwardly along the rises 626 and 630 to elevate that ring and thereby elevate those fingers.

The numeral 650 denotes an annular, friction-reducing sleeve that engages the inner periphery of the flange 504 on the body 500. That sleeve has a horizontally-directed flange 656 at the top thereof, and that flange rests upon the flange 504. The sleeve 650 and flange 656 are split, as at 651, to compensate for any manufacturing tolerances on the flange 504. The flange 656 of sleeve 650 has two arcuate slots 652 therein to accommodate the triangular stops 516 and to accommodate the upper ends of the pins 579 and the C-washers 585 carried thereby. Two

projections 654 are provided at the underside of the flange 656, as shown particularly by FIGS. 26 and 27; and those projections extend downwardly into the openings 522 in the flange 504. Those projections coat with those openings to hold the slots 652 in register with the stops 516 and the pins 579. The outer radius of the flange 656 on sleeve 650 is slightly less than the inner radius of the ridge 505, as shown by FIG. 37; and hence the outer periphery of flange 656 is disposed inwardly of that ridge and of the periphery of the wall 502.

The numeral 660 denotes a sleeve which telescopes within and abuts the inner face of the sleeve 650; and that sleeve has a horizontally-directed flange 662 projecting outwardly therefrom. The sleeve 660 is guided by the sleeve 650, and the flange 662 is supported by the flange 656. Two arcuate slots 664 are formed in the flange 662, and those slots are in register with, but have a greater angular extent than, the slots 652 in the flange 656. The greater angular extent of the slots 664 permits rotation of the sleeve 660 relative to the body 500 without causing the ends of the slots 664 to engage the stops 516 or the pins 579. The flange 662 has a notch therein with an inclined edge 663 at one end thereof; and that notch accommodates the rollers 290 and 314, as shown by dotted lines in FIG. 28. The sleeve 660 has arcuate abutments 665 that are similar to the abutments 506 on the body 500, and those abutments can be set in register with each other, as shown by FIG. 8. The sleeve 660 also has a horizontally-directed slot 671, and that slot is generally adjacent but above the level of the inclined edge 663. Further, the sleeve 660 has an outwardly projecting ear 672, as shown by FIG. 3.

The exterior of the sleeve 660 is provided with two flat faces 666 that are tangential to that exterior; and those flat faces are generally rectangular elevation, as shown by FIGS. 26 and 27. A small stud 668 extends radially outwardly from each of the flat faces 666; and a slot 670 is formed in each flat face 666 and in that portion of sleeve 660 below the face 666. A pivot 682 has a threaded end which seats in an opening in each of the flat faces 666, and that pivot is generally radially directed. An arm 684 is rotatably supported on each of those pivots, and the free ends of those arms carry pivots 686. Small rollers 688 are rotatably mounted on pivots 686; and studs 668 hold the arms 684 so the rollers 688 are always in register with the stops 516. Springs 690 are wound around pivots 682; and each spring has one end hooked under an arm 684 and has its other end thereof held by one end of a slot 664. The springs 690 bias the arms 684 to the position shown by FIG. 26, but they can yield to permit rotation of those arms to the position shown by FIG. 27.

The ear 672 on sleeve 660 has a vertically-directed, drilled and tapped opening that receives the lower end of a pin 678. A nut 676 is threaded on the lower end of that pin before that pin is threaded into the opening of the ear 672. The upper end of the pin is unthreaded, and it has a groove therein which receives and holds a C-washer 680.

The numeral 694 denotes a curved connecting rod with openings at both ends thereof. One opening of the connecting rod telescopes downwardly over pin 678, and it will be overlain by the C-washer 680. The opening at the other end of that connecting rod telescopes downwardly over pin 278. If desired, a C-washer could be mounted in a groove provided in the upper end of the pin 278 carried by the disc 264; and such a C-washer would prevent accidental separation of connecting rod 694 and pin 278. Inclined surfaces 695 are formed on the upper and lower faces of the rod 694, and that surface which is adjacent pin 278 will be adjacent the headed pin 272 when that headed pin moves away from the driven element 432.

The numeral 696 denotes securing plates with arcuate inner faces that are complementary to the periphery of

the flange 662; and those plates have transversely extending slots 697 to accommodate fasteners 698. Those fasteners extend down into the drilled and tapped openings in the cylindrical projections 511 and 509 atop the bosses 510 and the abutments 508 of the body 500. Those plates can be shifted until the inner ends of the slots 697 abut the shanks of the fasteners 698, and thereupon those plates will uncover and free the flange 662. On the other hand, those plates can be shifted until the outer ends of the slots 697 abut the shanks of the fasteners 698, and thereupon those plates will overlie, and prevent upward movement of, the flange 662.

Normal Positions of Movable Components

FIG. 1 shows the normal positions of several of the movable components of the cup dispenser of FIGS. 1 and 2; and, in particular, it shows the normal positions of disc 264, driven element 432, lever 492, sleeve 660, and lever 304. The position occupied by the cam 246 is the position which it occupies when the cup-separating head has only a limited number of cups in it and when the rest of the movable components of the cup dispenser are in their normal positions. As shown by FIG. 1, the pin 278 on disc 264 is acting through connecting rod 694 and through the pin 678 in the ear 672 on sleeve 660 to hold that sleeve adjacent its extreme counterclockwise position. The rollers 688, carried by the arms 684 on that sleeve, are held tightly against the vertical faces of stops 516; and thus they are held adjacent their lowermost positions and can hold the pins 579 down. Further, the abutments 665 on the sleeve 660 are adjacent their extreme counterclockwise positions, as shown by solid lines in FIG. 7; and, consequently, the cup-separating fingers 561, 560 and 572 are in the positions shown by FIGS. 7, 49 and 50. A cup 740 is resting on, and supported by, the closure 130, which is fully overlying and blocking the opening 104, and the cup 742 and the cups thereabove are supported by the four cup-separating fingers 560, 561. Closure 130 is in overlying position because the arm 220 is holding the roller 224 in the left-hand dotted-line position of FIG. 20.

The flange 662 of the sleeve 660 is adjacent its extreme counterclockwise position, and it has its notch in the dotted-line position shown by FIG. 28; and this means that the springs 236 and 322 are free to rotate the feelers 295 and 317 inwardly of the sleeve 660. In the position shown by FIG. 1, there are enough cups in the sleeve 660 to intercept and hold the feeler 317, but there are not enough cups to intercept and hold the feeler 295; and, consequently, the spring 286 has rotated the lever 282 and the cam 246 to the dotted-line positions of FIG. 28. Because the cam 246 is in the dotted-line position of FIG. 28, the rise 250 of that cam is holding the pin 272 so its head is a short distance above the top face of the ledge 270 on disc 264. However, that head is not as far above the top face of that ledge as that head will be when the disc subsequently moves to the position shown by FIGS. 14 and 16.

At this time, the projection 244 on the gear 238 is engaging and holding down the springy actuator 218 of the switch 216, and the motor in the motor housing 410 is de-energized. Further, the various composite cams 370-372 on the shaft 348 are in the normal, at-rest positions which are assigned to them by the operator or manufacturer of the coin-operated, drink-dispensing vending machine. Not until a patron inserts a coin in the coin slot 65 of that vending machine will the motor become energized and cause the shaft 348 to start rotating.

Operation

The rotation of the shaft 348 causes the composite cams 370-372 to pass through a cycle wherein they actuate the switches 396; but because those switches control the functioning of other components of the coin-operated, drink-dispensing vending machine and do not control the functioning of the cup dispenser, further discussion of

those cams and switches is unnecessary. The rotation of the shaft 348 acts through the crown gear 350 to rotate the crown gear 238; and the rotation of the latter gear rotates shaft 230 in the counterclockwise direction and 5 also rotates the crown gear 330 on shaft 332. This shaft is comparable to the shaft 348, but it is rotatably mounted in gear housing 384—a gear housing that is identical to the gear housing 336. Because the composite cams and switches in the gear housing 384 do not control the functioning of the cup dispenser, further discussion of those cams and switches also is unnecessary.

The counterclockwise rotation of the shaft 230 causes the pin 278 on the disc 264 to pull on the connecting rod 694, and that pull acts through the pin 678 in the ear 672 on sleeve 660 to rotate that sleeve in the counterclockwise direction. After the shaft 230 rotates approximately five degrees, the pin 278 is so close to one of its dead center positions that the sleeve 660 stops rotating; and that sleeve remains virtually motionless until the total rotation of the shaft 230 is between ten and fifteen degrees.

Shortly after the shaft 230 completes five degrees of rotation but before it rotates a total of ten degrees, the projection 244 moves out of engagement with the springy actuator 218 of switch 216, thereby enabling the switch 216 to establish a holding circuit for the motor in the motor housing 410. That holding circuit keeps that motor energized until the shaft 230 completes a full revolution and again moves the projection 244 into engagement with the springy actuator 218.

After the shaft 230 rotates counterclockwise for a total of approximately fifteen degrees, the pin 278 is beyond its dead center position, and the further rotation of that shaft causes that pin to push the connecting rod 694 and thereby cause the sleeve 660 to start rotating in the clockwise rotation. During the earlier rotation of the sleeve 660 toward its extreme counterclockwise direction, the pivots 682 moved even closer to the vertical faces of the stops 516; and that movement forced the rollers 688 down even further, and thus forced the pins 579 down even further. During the time the pin 278 was closely adjacent its said dead center position, the rollers 688 remained in their lowermost positions; but as the sleeve 660 begins rotating in the clockwise direction, the rollers begin to move upwardly along the vertical faces of the stops 516. 45 However, by the time the shaft 230 rotates a total of twenty degrees, the rollers 688 still have moved only a short distance upwardly.

At about this time, the roller 224 rotates beyond the bent end 135 of the arcuate cam surface 134; and thereupon the spring 138 pulls the closure 130 to its right-hand, solid-line position in FIG. 20. Thereupon, the cup 740, which has been resting upon that closure, falls downwardly through the discharge opening 104 and moves to a cup-filling station, not shown, in the vending machine. 55 Almost immediately thereafter, in accordance with the control action provided by the switches and cams in the cam housings 336 and 384, the various components of the vending machine direct the desired potables into that cup.

In moving to this position, the shaft 230 moved the disc 264 to and beyond the position shown by FIGS. 14 and 16. As that disc moved to the position shown by FIGS. 14 and 16, the pin 272 was raised even further by the rise 250 on cam 246; and the head of that pin engaged, and started to raise, the cam 499. By the time the shaft 230 completes a total of approximately twenty degrees of rotation, it has moved the disc 264 beyond the position of FIGS. 14 and 16, the pin 272 has reached the top of the rise 250, that pin has fully raised the cam 499 and lever 492, and the shank of the pin 272 has moved close enough to the driven element 432 to cause the head of that pin to overlie part of that driven element. After an additional two or three degrees of rotation of the shaft 70 230, which makes the total rotation of that shaft approxi-

mately twenty two or twenty three degrees, the shank of the pin 272 enters that slot of driven element 432 which has just been vacated by the cam 499, and the bottom of that shank passes beyond the rise 250 of the cam 246. While that pin is no longer held in raised position by the cam 246, that pin is held in raised position by the engagement of the head thereof with those portions of the driven element 432 which define the slot occupied by the shank of that pin. Hence, the pin 272 can not move downwardly and become separated from the driven element 432 until after that pin has completed the indexing of that driven element and has been moved out of the slot in that driven element.

By the time the shaft 230 has rotated a total of approximately forty-five degrees, the rollers 688 have moved upwardly against the studs 668, thereby permitting the springs 580 to move the lower cup-separating fingers 572 upwardly to the positions shown by FIGS. 3 and 52. At this time, the rollers 688 are immediately adjacent the vertical faces of the stops 516, and the cup-separating fingers 560, 561 and stack-supporting fingers 587 are in the positions shown by FIGS. 7 and 51. Also at this time, the abutments 665 on the sleeve 660 have rotated to the positions shown by dotted lines in FIG. 7. Further at this time, the driven element 432 has rotated the turret of the cup dispenser somewhat more than thirty degrees about its axis.

After the shaft 230 has rotated a total of approximately forty-seven degrees, the inclined surface 663 at one side of the notch in the flange 662 moves into engagement with the roller 290 and causes the lever 282 to start moving toward the solid-line position of FIG. 28. As the lever 282 starts rotating in the counterclockwise direction, the connecting rod 294 causes the cam 246 to start rotating in the clockwise direction. At this time the roller 314 is still adjacent the bottom of the notch and is still spaced from the inclined edge 663.

After shaft 230 has rotated a total of approximately fifty degrees, the abutments 665 on sleeve 660 have moved far enough clockwise to permit stack-supporting fingers 587 to start moving inwardly. Those fingers are biased for such movement by springs 590. The shoulders 596 of those fingers are below the level of the rim of cup 742 held by cup-separating fingers 560 and 561, and will thus be able to move under that rim.

Further counterclockwise rotation of shaft 230 causes driven element 432 to continue to rotate the turret, but by the time the shaft 230 has rotated a total of approximately eighty-five degrees, the turret has rotated sixty degrees and has come to rest. At this time the shank of pin 272 has moved out of the slot which it occupied; and after an additional five degrees of rotation of shaft 230, the head of pin 272 has moved beyond the periphery of driven element 432. Thereupon, that pin will be able to move downwardly in opening 268 of ledge 270 on disc 264. As pin 272 moved out of the slot which previously had been occupied by cam 499, that slot moved into register with pin 496 on lever 492 and the next-successing slot moved into register with cam 499. Thereupon that cam, which had been held in raised position by the portion of the driven element intermediate those slots, move down into that next-successing slot and again locks that driven element. In the event the pin 272 does not move promptly, the adjacent inclined surface 695 on the under side of connecting rod 694 will engage the head of that pin and move that pin downwardly, thereby avoiding a jam.

As the turret neared the end of its sixty degrees of rotation, it moved a fresh stack of cups into register with opening 441 in the support 438; and thereupon that stack of cups moved downwardly through that opening toward the cups held by the lips 570 on cup-separating fingers 560 and 561. The lowermost cups of that stack of cups engaged the feeler 295 of the lever 282 as they moved

downwardly because, while the engagement of the inclined edge 663 with the roller 290 had started moving that feeler outwardly, the movement of that inclined edge relative to that roller had not been extensive enough to move the feeler 295 out of the path of those cups. By engaging the feeler 295, those cups dissipated some of their kinetic energy; and, as a result, those cups did not dislodge the cups resting upon, and supported by, the lips 570 of the cup-separating fingers 560 and 561. If the cups in that stack of cups are small diameter cups, those cups will be freed of engagement with the feeler 295 by the time the shaft 230 has rotated a total of approximately ninety degrees; but if those cups are large diameter cups, those cups will not be freed of engagement with that feeler until the shaft 230 has rotated approximately one hundred degrees. In each of those positions of the shaft 230, the roller 290 will be engaged and held outwardly by the inclined edge 663 of the notch in flange 662; and in the latter position, the feeler 295 will be held closely adjacent the inner periphery of the sleeve 660. In that latter position, the lever 282 will be holding the cam 246 close to the solid-line position of FIG. 28.

When the shaft 230 reaches a position of approximately ninety-five degrees, the inclined edge 663 of the notch in flange 662 engages the roller 314 on lever 304 and starts moving that lever toward the solid-line position of FIG. 28. In that position the lever 304 has the apron 318 out of engagement with the switch button 334 of switch 330. At this time, the roller 290 is still in engagement with that inclined edge and the lever 282 and the cam 246 are still short of their fully moved positions. Also at this time, if the cups are large diameter cups, the stack-supporting fingers 587 have moved all the way into stack-supporting position. However, if those cups are small diameter cups, the stack-supporting fingers 587 will not move all the way into stack-supporting position until the shaft 230 has rotated a total of approximately one hundred and five degrees. Regardless of the particular instant when the abutments 665 move far enough in the clockwise direction to permit the stack-supporting fingers 587 to move all the way into stack-supporting position, the cup-separating fingers 560 and 561 will still be supporting the cup 742 and the cups thereabove; and hence all the stack-supporting fingers 587 do at that instant is place the shoulders 596 thereof in position to intercept and hold the rim of the cup 742 when that cup is released by the cup-separating fingers 560 and 561. When the stack-supporting fingers 587 are in their innermost positions, the cup-separating and stack-supporting fingers are in the positions shown by FIGS. 8, 53 and 54.

When the shaft 230 has rotated a total of approximately one hundred and five degrees, the abutments 665 on sleeve 660 will, if the cups are small diameter cups, engage the cup-separating fingers 560 and 561 and start rotating them outwardly toward the cylindrical wall 502. However, if those cups are large diameter cups, the abutments 665 will not engage and start to move the cup-separating fingers 560 and 561 outwardly until the shaft 230 has rotated a total of approximately one hundred and thirty degrees. However, regardless of the particular instant when the abutments 665 engage the cup-separating fingers 560 and 561 and start to move them outwardly, those fingers will, prior to the time the shaft 230 has rotated a total of one hundred and seventy five degrees, move their lips 570 wholly out of engagement with the rim of the cup 742 and permit that cup and the cups thereabove to move downwardly. The rim of the cup 742 will, almost immediately, be intercepted and held by the shoulders 596 on the stack-supporting fingers 587; and at such time, those fingers will constitute the support for the stack of cups. The shaft 230 will usually have to rotate in the neighborhood of from ten to fifteen degrees between the time the cup-separating fingers 560 and 561 start to move outwardly and the time when the lips 570 of those fingers release the rim of the cup. When the

lowermost cup of the stack of cups is released by the cup-separating fingers, that cup and the cups thereabove are free to move downwardly because the diametric distances between the cylindrical surfaces 589 of the oppositely disposed stack-supporting fingers 587 are greater than the outer diameters of the rims of the cups. Furthermore the tapering of those cylindrical surfaces facilitates the uninterrupted downward movement of those cups. As the rim of the cup 742 approaches the shoulders 596 of the stack-supporting fingers 587, the upper portions of the sides of that cup are engaged and guided by the frusto-conical surfaces 594 on those fingers. Moreover, after the rim of that cup comes to rest on those shoulders, those frusto-conical surfaces will be immediately adjacent the sides of, and will steady, that cup.

In moving downwardly, the cup 742 and the cups thereabove were unhindered by the feeler 295 of lever 282 or the feeler 317 of lever 304. This is due to the fact that the inclined edge 663 engages the rollers 290 and 314 and starts them, and the feelers 295 and 317 moving outwardly before the abutments 665 even engage the cup-separating fingers 560 and 561 and start them moving outwardly. In particular, depending upon the diameters of the cups and thus the cup-engaging positions of the cup-separating fingers 560 and 561, the roller 290 starts outwardly from fifty-eight to eighty-three degrees before the cup-separating fingers 560 and 561 start outwardly, and the roller 314 starts outwardly from ten to thirty-five degrees before those fingers move outwardly. Moreover, both the feelers 295 and 317 move wholly outwardly beyond the inner periphery of the sleeve 660 before the lips 570 on the cup-separating fingers 560 and 561 do so.

At the time the shaft 230 had rotated just a total of approximately one hundred and thirty degrees and had caused the inclined edge 663 of the notch in the flange 662 to move the feeler 295 to its outermost position, that shaft also acted through lever 282 and connecting rod 294 to rotate the cam 246 to the solid-line position of FIG. 28. Thereafter the further rotation of the shaft 230 caused the periphery of the flange 662 on sleeve 660 to hold the roller 290 and the feeler 295 in their outermost positions and also acted through lever 282 and connecting rod 294 to continue to hold the cam 246 in that solid-line position. Also by the time the shaft 230 had rotated a total of approximately one hundred and thirty degrees, the inclined edge 663 had caused the roller 314 to rotate the lever 304 far enough in the clockwise direction to move the apron 318 on that lever out of engagement with the button 334 of the switch 330. However, it is not until the shaft 230 has rotated a total of approximately one hundred and seventy-five degrees that the inclined edge 663 causes the roller 314 to move the lever 304 to its extreme clockwise position; and at that time the roller 314 will be at the outer end of the inclined edge 663 and the feeler 317 will be disposed wholly outwardly of the area defined by the inner periphery of the sleeve 660. As the sleeve 660 rotated in the clockwise direction to enable the edge 663 to move the roller 314 all the way out to its outermost position, the roller 290 rested against that portion of the periphery of flange 662 which is beyond the notch. That portion of the periphery is concentric with the axis of rotation of the sleeve 660, and therefore that rotation did not change the position of the lever 282 or of the cam 246.

When the shaft 230 has rotated approximately one hundred and seventy-five degrees, the abutments 665 will have rotated the cup-separating fingers 560 and 561 outwardly adjacent the cylindrical wall 502, as shown by FIGS. 9, 55 and 56. Those fingers will remain in that position, and the sleeve 660 will remain stationary, as the pin 278 moves through the other of its dead center positions. After that pin has passed through that dead center position it will pull the connecting rod 694 and start the sleeve 660 rotating in the counterclockwise direction.

When the shaft 230 reaches approximately one hundred and eighty-five degrees, the abutments 665 start moving away from the cup-separating fingers 560 and 561 to permit those fingers to move back toward cup-engaging position.

By the time shaft 230 has rotated a total of approximately two hundred and ten degrees, the roller 224 has moved back into engagement with arcuate cam surface 134 on closure 130, and flange 662 has rotated far enough in the counterclockwise direction to permit roller 314 to start moving inwardly along inclined edge 663. At this time, the roller 224 is in the right-hand, dotted-line position shown in FIG. 20, and further rotation of shaft 230 enables that roller to start moving that closure toward its left-hand, dotted line position in FIG. 20. Also at this time, the roller 314 is ready to respond to spring 286 and to further rotation of shaft 230 to move inwardly and move feeler 317 inwardly of the sleeve 660. As the shaft 230 reaches an angle of approximately two hundred and forty degrees, the feeler 317 on lever 304 will have moved far enough inwardly to engage the side or rim of a cup having a large diameter. At this time, the disc 264 carries the pin 272 over the lowermost end of the rise 250 on cam 246. The level of that lowermost end is below that of the bottom of the pin 272, and hence that pin does not, at this time, engage that rise.

By the time the shaft has rotated a total of approximately two hundred and fifty degrees, the abutments 665 have moved far enough to permit the cup-separating fingers 560 and 561 to rotate into position to engage the stack of cups, if the cups are large diameter cups. However, if those cups are small diameter cups, the shaft 230 will have to rotate an additional five degrees to enable the cup-separating fingers to engage those cups. Irrespective of the particular instant when those fingers engage those cups, the lips 570 of those fingers and the lips 576 of the fingers 572 will move into the space between the rim of cup 742 and the rim of cup 744. The stack of cups is still supported by the shoulders 596 on the stack-supporting fingers 587; and therefore the cup-separating fingers 560 and 561 are, at this time, merely moving into position to intercept and hold the rim of cup 744 when the stack-supporting fingers 587 no longer hold the cup 742.

When the shaft 230 has rotated a total of approximately two hundred and fifty-five degrees, the inclined edge 663 of the notch in flange 662 re-engages the roller 290 on lever 282 and permits the spring 286 to start rotating that lever in the clockwise direction. As the lever 282 so rotates, it causes the cam 246 to rotate in the counterclockwise direction. However, the inclined edge 663 merges so smoothly with the outer periphery of the flange 662 that very little movement of the lever 282 and of the cam 246 occurs until the shaft 230 has rotated considerably further.

When the shaft 230 has rotated a total of approximately two hundred and sixty-five degrees, the roller 224 has shifted the closure 130 far enough toward its left-hand, dotted-line position in FIG. 20 to keep a large diameter cup from passing through the discharge opening 104. By the time the shaft 230 has rotated a total of approximately two hundred and seventy degrees, the roller 224 has shifted the closure into a position where it can block the passage, through the discharge opening 104, of even small diameter cups. At this time the lowermost cup of the stack of cups is, regardless of its size, solidly supported by the shoulders 596 of the stack-supporting fingers 587; and this means that prior to the time that lowermost cup can be freed from that stack and can move downwardly toward the discharge opening 104, the closure 130 is effectively blocking that opening.

After the closure 130 has been moved into position to block the passage, through opening 104, of even small diameter cups, the abutments 665 start moving the stack-supporting fingers outwardly. The shaft 230 will then have to rotate, depending upon the diameters of the cups

and the resulting cup-engaging positions of the stack-supporting fingers 587, in the neighborhood of from ten to fifteen degrees before the shoulders 596 on those fingers move out of engagement with the rim of the cup 742. Even after the cup 742 has been released, the abutments 665 will continue to move the stack-supporting fingers 587 outwardly; and those fingers will reach their outermost positions when the shaft 230 has rotated a total of approximately three hundred and thirty degrees.

At the time the shoulders 596 of the stack-supporting fingers 587 moved out from under the rim of the cup 742, that cup was free to move downwardly, and usually that cup will free itself from the cup 744 and move downwardly and rest upon the closure 130; but in some cases the cup 742 will cling to and remain in engagement with the cup 744. That latter cup, and the cups thereabove, will, however, move downwardly a short distance until the rim of that latter cup rests upon the lips 570 of the cup-separating fingers 569 and 561.

At the time the shaft 230 had rotated a total of approximately two hundred and seventy degrees, the roller 314 on the lever 304 had moved far enough inwardly along the inclined edge 663 on the flange 662 to cause the feeler 317 to engage the side or rim of even a small diameter cup. If that feeler had engaged the side or rim of a large diameter cup, when the shaft 230 had rotated just a total of approximately two hundred and forty degrees, the feeler 317 and the lever 304 would have been unaffected by the further rotation of the shaft 230, because that feeler would have been held against further inward movement by that cup. Similarly, if the feeler 317 engages the side or rim of a small diameter cup when the shaft 230 has rotated two hundred and seventy degrees, the rotation of the shaft 230 during the rest of the cycle will not affect the position of the feeler 317 and of lever 304 because that feeler will be held against further inward movement by that cup. Regardless of the particular instant when the feeler 317 on lever 304 engages and is held against further inward movement by the side or rim of a cup, that lever is held so the apron 318 thereof is spaced from the button 334 on the switch 330. Consequently, the empty lamp of the vending machine will not be energized; and it is only when the feeler 317 fails to engage and be held by a cup that the apron 318 engages and actuates the switch button 334.

By the time the shaft 230 had rotated a total of approximately two hundred and seventy degrees, the bottom of the pin 272 had engaged the rise 250 on the cam 246; and that pin was urged upwardly by that rise. At that time, that cam was close to the solid-line position of FIG. 28; but that cam continued to move toward the dotted-line position of FIG. 28 as the continued counterclockwise rotation of the flange 662 permitted the roller 298 to move inwardly along the inclined edge 663. If large diameter cups are being dispensed, the side or rim of one of those cups will intercept and hold the feeler 295 on lever 282 after the shaft 230 has rotated a total of approximately two hundred and eighty-five degrees; and thereafter that feeler and lever will be held against further inward movement, and the cam 246 will be held against further movement toward the dotted-line position shown by FIG. 28. If small diameter cups are being dispensed, the side or rim of one of those cups will intercept the feeler 295 of lever 282 after the shaft 230 has rotated approximately three hundred degrees; and thereafter that feeler and lever will be held against further inward movement, and the cam 246 will be held against further movement toward the dotted-line position shown by FIG. 28. Whether the feeler 295 on lever 282 engages a large diameter cup or engages a small diameter cup, it will be held in a position that will keep the cam 246 out of the dotted-line position shown by FIG. 28. This means that as the shaft 230 approaches the end of its cycle, it will be unable to keep the pin 272 in raised position. Instead, that shaft will cause that pin to engage and pass by the rise 250 on cam

246 well before the end of the cycle. In particular, the shaft 230 will cause the pin 272 to move upwardly as it passes along the rise 250 of cam 246 and then drop downwardly as the bottom of that pin passes beyond and out of engagement with the rise 250; and all of this before the end of the cycle. This is desirable because a full stack of cups is already in register with the cup-separating head and it would be undesirable to index the turret and thereby move still another fresh stack of cups toward the cup-separating head. The pin 272 will be free to, and should, drop down until its head rests upon the ledge 270 of disc 264. However, in the event gravitational forces do not move that pin all the way down, that pin will be moved all the way down when it engages the cam 499 on lever 492; the leading edge of that cam guiding the head of the pin 272 down below the level of the driven element 432. Consequently, during the next cycle, the pin 272 will pass below, and will not rotate, the driven element 432.

By the time the shaft 230 has rotated a total of approximately three hundred and fifteen degrees, the rollers 688 have been moved into engagement with the vertical faces of the stops 516. Further counter clockwise rotation of the shaft 230 causes the rollers 688 to move toward their lowermost positions; and that movement causes the pins 579 and the lower cup-separating fingers 572 to move to the positions shown by FIG. 50. In moving to those positions, those cup-separating fingers make certain that the cup 742 frees itself from the cup 744 and moves down onto the closure 130. The downward movement of the cup-separating fingers 572 is great enough to fully and completely free the cup 742 from the cup 744. At this time, the cup-separating fingers 569 and 561 and the stack-supporting fingers 587 are again in the positions shown by FIGS. 49 and 50, but it is the cup 742 which is resting on the closure 130 instead of the cup 740, as shown by FIGS. 49 and 50. Also at this time, the holding circuit which was established when the projection 244 moved out of engagement with the springy actuator 213 is broken by the re-engagement of that projection with that actuator. Consequently, the motor becomes de-energized; and it will remain de-energized until another coin is inserted in the coin slot of the coin-operated, drink-dispensing vending machine. Also at this time, the roller 224 has moved the closure 130 to the left-hand, dotted-line position of FIG. 20; and that closure will remain in that position and support the cup 742 until after the start of the next cycle of operation of the cup dispenser.

As the shaft 230 passed through its first cycle, it released the cup 740, it indexed the turret to supply a fresh stack of cups to the cup-separating head, and it separated the cup 742 and caused it to come to rest on the closure 130. As the shaft 230 passes through its second cycle, it will release the cup 742, it will permit the turret to remain motionless, and it will separate the cup 744 and cause it to come to rest on the closure 130. Successive cycles of operation of the shaft 230 will provide prompt delivery of the previously separated and held cups and will, toward the ends thereof, separate and hold cups for release during the following cycles. When the rim of the uppermost cup in the stack of cups in the sleeve 660 is again below the level of the feeler 295 on lever 282, that feeler will not be held out during the last quarter of the cycle of the shaft 230; and, instead, it will move inwardly to the dotted-line position of FIG. 28. As that feeler moves to that position, the lever 282 and the connecting rod 294 will move the cam 246 to the dotted-line position of FIG. 28. Consequently the pin 272 will be resting upon, and will be partially raised by, the rise 250 of that cam at the end of that cycle. At the start of the next cycle of the shaft 230, the pin 272 will move further upwardly along the rise 250, enter the adjacent slot of the driven element 432, and then index the turret to place a fresh stack of cups in register with the cup-separating head, all as explained above.

If the time arrives when the turret is completely out

of cups, the pin 272 will index that turret during each of the few remaining cycles of shaft 230 before the uppermost cup moves down below the level of the feeler 317 on the lever 304. With average size cups, this means that the shaft 230 will pass through approximately four cycles between the time the feeler 295 on lever 282 feels no cups and the time the feeler 317 on lever 304 feels no cups, because five average size cups must be stacked in the cup-separating head 500 to hold out the feeler 317 on lever 304 and nine such cups must be stacked in that head to hold out the feeler 295 on lever 282. Regardless of the number of cycles required, the supply of cups can become so depleted that the feeler 317 on lever 304 can fail to engage and feel a cup. Thereupon that feeler will respond to the spring 322 to move inwardly to the dotted-line position of FIG. 28; and at that time, the lever 304 will hold its apron 318 in engagement with the button 334 of switch 330 and enable that switch to illuminate the empty lamp, and to actuate the coin-rejection circuit, of the vending machine.

When the service man next makes his rounds, he will remove the cover 480 from the turret and fill that turret with fresh stacks of cups. Those stacks will, in the case of all stacks that are out of register with the opening 441 in the support 438, come to rest upon the friction-reducing ribs 442 atop that support. The cups of the stack in register with that opening will move downwardly toward the few cups that are held in the head 500 but that have their rims below the level of the feeler 317. Because a stack of cups moving downwardly a distance equal to the height of the turret can develop appreciable kinetic energy, and could thereby bend the feelers 295 and 317, it is customary for the service man to manually move the levers 282 and 304 outwardly until their feelers are out of the path of the stack of cups, and to hold those levers outwardly until the stack of cups is fully seated on the cups already in the cup-separating head 500. When the service man releases the levers 282 and 304, the springs 286 and 322 will move the feelers 295 and 317 against the cups of the newly inserted stack of cups; and at that time, the cam 246 will be out of the dotted-line position of FIG. 28 and the apron 318 will be out of engagement with the button 334 on the switch 330. As a result, the coin-operated, drink-vending machine is again ready to vend. After the supply of cups has been replenished, the cup dispenser of FIGS. 1 and 2 is capable of dispensing in excess of six hundred cups without any supervision or attention.

The abutments 506 at the inner periphery of annular flange 504 on the head 500 can serve, during the operation of the cup dispenser, as stops for cup-separating fingers 560 and 561. For example, when the abutments 665 on sleeve 660 move to the position of FIG. 7, those abutments are wholly out of engagement with the cup-separating fingers 560 and 561; and the resistance to unlimited clockwise rotation of those fingers can be supplied by the abutments 506. Actually, the abutments 506 will serve as stops only when the cup-separating head 500 is completely empty or when cups are used which are small enough in diameter to permit the cup-separating fingers 560 and 561 to rotate far enough inwardly to engage those abutments. Where, as in the case in FIG. 10, large diameter cups are to be dispensed, the rims of those cups will, themselves, resist and limit the clockwise rotation of the cup-separating fingers 560 and 561.

In contrast to the cup-separating fingers 560 and 561, the stack-supporting fingers 587 are not limited in their inward rotation by the rims of the cups; instead, as shown by FIG. 9, those stack-supporting fingers are limited in their inward rotation by the engagement of the studs 598 thereon with the pins 636 on the positioning ring 634. Even when the adjusting lever 538 is set in its zero position, the pins 636 hold the stack-supporting fingers 587 out of engagement with the abutments 506. As a

result, precise control of the inner positions of the stack-supporting fingers 587 is readily attained.

The diameters of the cups to be dispensed will not only determine the setting of the inner positions of the stack-supporting fingers 587, and will not only determine how far inwardly the cup-separating fingers 560 and 561 can rotate, but those diameters will also determine the timing, during the cycle of operation of the shaft 230, of the outward movement of those fingers. Thus, the stack-supporting fingers 587 start moving outwardly approximately fifteen degrees sooner in a cycle where they support the smallest diameter cups than they do where they support the largest diameter cups. Even more strikingly, the cup-separating fingers 560 and 561 start moving outwardly approximately twenty five degrees sooner in a cycle where they support the smallest diameter cups than they do where they support the largest diameter cups. However, as pointed out above, irrespective of the diameter of the cups being dispensed, no cup is ever released for movement toward the discharge opening 104 until after the closure 130 has moved into position to block the passage of that cup through that opening.

In setting the inner positions of the stack-supporting fingers 587, the operator first removes all of the cups in register with the cup-separating head 500; and he does this very easily and quickly by starting a cycle of the vending machine and shutting off the power when the abutments 665 have moved the cup-separating fingers 560 and 561 to the position of FIG. 9, and then loosening nut 552 and rotating lever 538 into register with numeral "55" on dial 540. That rotation enables cam 536 to shift positioning ring 634 far enough in the clockwise direction to move shoulders 596 and frusto-conical surfaces 594 on the stack-supporting fingers 587 wholly outwardly of the inner periphery of sleeve 660. Thereupon, all of the cups in register with sleeve 660 pass downwardly and out of the cup-separating head 500. The cups in the other compartments of the turret can be removed by hand or by cycling the vending machine five times. The numerals and graduations on the dial or panel 540 then enable the operator to rotate lever 538 to the proper position and tighten nut 552. However, if the operator does not know or does not remember the numeral corresponding to the desired setting, he can still attain the required setting easily and quickly. That operator will rotate lever 538 to the zero position, insert a few cups of the desired size and then slowly rotate lever 538 in the clockwise direction until those cups drop down and seat the lowermost cup thereof on the shoulders 596 of stack-supporting fingers 587. The operator will thereupon move lever 538 clockwise past two additional graduations and tighten nut 552. That additional rotation made certain that it is the frusto-conical surfaces 594 and not the cylindrical surfaces 589 that engage the cups.

If the new cups have diameters that are appreciably different from the diameters of the discontinued cups, it will be desirable to check, and it may be essential to adjust, the vertical spacing between the upper surfaces of the lips 60 570 on the cup-separating fingers 560 and 561 and the shoulders 596 on the stack-supporting fingers 587. The numerals, "1," "2" and "3" on the dial or panel 540 indicate the three basic positions of the knurled set screw 623, and thus of the positioning ring 634. Consequently, the operator need only loosen the knurled set screw 623, shift that set screw into register with the numeral corresponding to the new cup, and then tighten that set screw. Thereafter the operator can restore the power to the vending machine and can fill the turret; and thereupon the vending machine will again be ready to vend drinks. However, if the operator does not know or can not remember the numeral corresponding to the new cup, he should shift the set screw 623 into register with the numeral "3" on panel 540, insert just one cup, and then restore the power until 70 the cup-separating fingers 560 and 561 and the stack-sup-

porting fingers 587 are in the positions of FIG. 8. Thereafter, he can grasp the bottom of that cup and shift that cup up and down while moving the set screw 623 to rotate the cam ring 620. When the amount of possible vertical movement has been reduced to less than one thirty second of an inch, he can re-tighten the set screw 623; and thereupon he can restore power and can fill the cup dispenser with cups. The three basic setting for the positioning ring 634, as indicated by the numerals "1," "2" and "3," will provide most of the vertical spacings required; but where other vertical spacings are required, the shallow, inclined rises 626 and 630 provide them. As a result, the cam ring 620 can provide each and every vertical spacing that is required.

As indicated by FIG. 25, vertical surfaces define and bound those ends, of the low dwells 624, which are remote from the shallow, inclined rises 626; and the lower ends of the pins 636 on the positioning ring 634 can be set adjacent those vertical surfaces. As a result, the rotation of the lever 538 to its extreme clockwise position, during the emptying of the cup-separating head 500, can cause those pins to move against those vertical surfaces. The forces exertable by the lever 538, through the cam 536, are great enough to cause the set screw 623 to slide relative to the flange 612 on the tube 610; and consequently, the cam ring 620 can move circumferentially to permit the shafting of the positioning ring 634 to head-emptying position.

The numeral "1" on the dial 540 corresponds to the smallest vertical spacing between the upper surfaces of lips 570 and the shoulders 596; and the numeral "3" corresponds to the greatest vertical spacing between those surfaces and those shoulders. Consequently, if the set screw 623 is shifted from a position adjacent numeral "1" to a position adjacent numeral "2" or numeral "3," the cam ring 620 will be rotated in the counterclockwise direction and will present the dwells 628 or the dwells 624 to the pins 636 on the positioning ring 634. Thereupon that positioning ring will respond to the downwardly-directed forces applied to it, through the medium of the stack-supporting fingers 587, by the springs 606 and move downwardly until the pins 636 engage and are held by the cam ring 620. Conversely, if the set screw 623 is shifted from a position adjacent the numeral "3" to a position adjacent the numeral "2" or the numeral "1," the positioning ring 634 will be raised upward by the rise 626 or by the rises 626 and 628 and will further compress the springs 606.

During the operation of the cup dispenser, the two cup-separating fingers 572 rotate with the two cup-separating fingers 560 with which they are concentric, but they also move vertically relative to those latter fingers. Specifically, the two cup-separating fingers 572 move upwardly and abut the bottom faces of the two said cup-separating fingers 560 shortly after the start of a cycle, and then they move downwardly and away from those bottom faces shortly before the end of that cycle. In moving upwardly, the cup-separating fingers 572 make it possible for the lips 574 thereof to be subsequently moved into position above the rim of the lowermost cup of the stack of cups; and in moving downwardly, those cup-separating fingers positively separate that cup from the stack of cups and direct it toward the closure 130. The two cup-separating fingers 561 are not provided with lower cup-separating fingers 572, because the two cup-separating fingers 572 are adequately able to force the lowermost cup to move downwardly. Those two cup-separating fingers 561 do, however, perform an important function in helping hold the cups level and steady.

During the operation of the cup dispenser, the springs 282 and 322 recurrently rotate the feelers 295 and 317, respectively, into engagement with the rims or the sides of the cups supported within the cup-separating head 500; and those springs are strong enough to provide prompt

and full inward movement of those feelers. However, those springs are weak enough not to bend or injure any of the cups; and hence, if a cup is in the path of either the feeler 295 or the feeler 317, that cup will easily prevent full inward movement of that feeler.

During the operation of the cup dispenser, the sleeve 669 rotates approximately thirty-eight degrees in each direction. To enable the flange 662 on that sleeve to rotate that far and yet not strike the stops 516 or the pins 579, the arcuate slots 664 in that flange are given an angular extent of approximately eighty degrees. Such an angular extent accommodates the full rotation of the sleeve 669 and still leaves open areas at the ends of those slots in the extreme clockwise and counterclockwise positions of that sleeve.

During the indexing of the turret, to replenish the supply of cups for the cup-separating head 500, the driven element 432 rotates relative to the disc 264. Because the portions of that driven element, which are intermediate the slots of that element, have concave peripheries, the portions of that driven element which define the slots have radii that are larger than the distance between the center of pivot 430 and the periphery of the disc 264. Those larger radii portions of the driven element 432 of the Geneva gear are fully accommodated by the recess 276 which is provided in the disc 264 adjacent the pin 272. Consequently, jam-free rotation of the driven element 432 is assured.

The rise 250 on the cam 246 will raise and then release the pin 272 during each and every cycle of operation of the cup dispenser. However, that rise will move the pin 272 into one of the slots of the driven element 432 of the Geneva gear only during those cycles of operation which follow cycles of operation wherein the feeler 295 fails to engage and be held by a cup. During all of the other cycles of operation of the cup dispenser, the feeler 295 will engage and be held by a cup and will hold the cam 246 out of the dotted-line position of FIG. 9; and, as a result, the pin 272 will be spaced away from the driven element 432 when it is at the top of the rise 250, and that pin will be wholly below the level of that driven element when it approaches that driven element. Consequently, only when indexing of the turret is needed will the cam 246 move the pin 272 into engagement with the driven element 432.

Ten Stack Turret

FIGS. 2, 3, 5, 6 and 33 disclose the various components of a turret that can accommodate six stacks of cups; and such a turret is very useful. However, some coin-operated, drink-dispensing, vending machines require even more cups than can be accommodated by a six stack turret. For such vending machines, the present invention provides a ten stack turret; and the present invention makes it possible to use that larger turret with the gear housing, the cam housing, the motor housing, and the cup-separating head used with the six stack turret. All that needs to be done is to replace the disc 264 with the disc 702 of FIG. 17, to replace the driven element 432 with the driven element 700 of FIG. 17, to shift the pin 260 from the hole 258 in cam 246 to the hole 256 in that cam, to shift the pivot 430 from the opening 200 in the boss 198 to the opening 204 in the boss 202, to shift the yoke 482 to the opening 200 in the boss 198, to add an additional strut 450, to replace the support 438 with a larger support, and to replace the six stack turret with the ten stack turret. That larger turret will be similar to, but larger than, the six stack turret. For example, that turret will have a polygonal plate with depending flanges; but instead of having six such flanges, as does the plate 468, that polygonal plate will have ten such flanges. The ten stack turret will have ten instead of six bent plates 470, it will have larger diameter upper and lower rings, it will have a larger transparent sleeve, and it will have a larger cover. The additional strut 450

will be secured to the gear housing 144 by a fastener 454 seated in the opening 159 in ledge 158, and it will be suitably secured to the larger support that replaced the support 438. The remaining struts will be rotated slightly about the axes of the fasteners 454, securing them to the ledges 158 and 184, to render the spacing between the upper ends of those struts generally uniform; but that rotation is easily accomplished. The discharge opening of the support for the ten stack turret will be, as is the case with the opening 441 of support 438, in register with the sleeve 660.

With the base of the yoke 482 seated in the opening 200 of the boss 198, the lever 492 will be rotated one hundred and eighty degrees about the pivot 490; and at such time the cam 498 and the pin 494 thereon will be at the lower face of that lever. Further, as shown by FIG. 17, that cam and that pin will be lodged in two of the slots in the driven element 700. That driven element is similar to the driven element 432 but it has ten slots and ten openings 701, whereas the driven element 432 has six slots and six openings 434. The pin 494 will respond to forces, applied by the sides of the slot in which it is located, to resist clockwise rotation of lever 492 and yoke 482; much in the same way in which the pin 496 resisted counterclockwise rotation of that lever and yoke when that lever and yoke were used with the driven element 432.

As indicated particularly by FIGS. 28 and 32, the geometric center of the opening 204 in boss 202 is further from the axis of the shaft 230 than is the geometric center of the opening 200 in boss 198. Further, the diameter of the disc 702 is smaller than the diameter of the disc 264; and the difference between the two diameters coacts with the difference in spacing between shaft 230 and the centers of the openings 200 and 204 to make it possible to drive the larger diameter driven element 700 of the Geneva gear by means of the same shaft 230. The driven element 700 has an upwardly extending flange at the top thereof and has a downwardly extending flange at the bottom thereof, and those flanges are comparable to the upwardly extending and downwardly extending flanges on the driven element 432. The ten openings 701 are comparable to the six openings 434 in the driven element 432, but those openings are set closely adjacent the diameters that are in register with the slots in the driven element 700. However, those openings are dimensioned and spaced to accommodate and receive the bosses 464 on the hub 460 of the ten stack turret. The portions of the periphery of the driven element 700 intermediate the ten slots are concave, and those portions have radii which are slightly larger than the radius of the disc 702. That disc has a recess 710 which is adjacent the ledge 706, of reduced thickness, on that disc; and that recess accommodates, during indexing of the turret, those portions of the periphery of the driven element 700 which define the outer ends of the slots. The disc 702 also has a generally D-shaped recess 704 in the top thereof; and a pin 712 projects upwardly from the wall that defines that recess. The pin 712 is spaced circumferentially from the position which is occupied by the pin 278 on the disc 264. Specifically, the pin 712 is adjacent the leading edge of the recess 710 of disc 702 whereas the pin 278 is adjacent the trailing edge of the recess 276 of disc 264. The ledge 706 of the disc 702 carries a headed pin 708 which is identical to the headed pin 272. The disc 702 is comparable to, and performs the same functions as, the disc 264.

The disc 702 will be suitably fixed on the upper end of the shaft 230, and one of the openings in the connecting rod 694 will be telescoped down over the pin 712. The other opening in that connecting rod will be telescoped down over the pin 678 carried by the ear 672 on sleeve 660. That connecting rod will enable the rotation of the disc 702, by the shaft 230, to oscillate the sleeve 660; and during that oscillation a cup will be sep-

arated in the manner described above in connection with the six stack turret. Also during the oscillation, the feeler 295 will feel for the presence of cups in the cup-separating head 500. If that feeler engages and is held by a cup, it will cause the lever 282 to hold the cam 246 in a position where the lower end of the rise 250 is adjacent the switch bracket 324 and where the upper end of that rise is spaced in the neighborhood of from twenty to thirty degrees from the periphery of the driven element 700. Where that is the case, the pin 708 will be raised and then released by the rise 250 on cam 246 at a time when that pin is spaced wholly away from the driven element 700; and, consequently, that pin will pass below and not engage that driven element. However, if that feeler does not engage a cup, it will permit the spring 286 to act through lever 282 and connecting rod 294 to rotate the cam 246 to the position of FIG. 17; and in that position, the cam 246 has the top of its rise 250 closely adjacent the periphery of the driven element 700. As a result, the pin 708 will be elevated by and will be resting upon the rise 250 at the end of a cycle of operation of the cup dispenser. After the start of the next cycle of operation of that cup dispenser, the pin 708 will be moved even further along the rise 250 of the cam 246, as indicated by FIG. 17; and that pin will be raised even further upwardly as it does so. As a result, by the time the pin 708 is adjacent the driven element 700, that pin is sufficiently elevated for the head thereof to overlie the top of the driven element 700 and for the shank thereof to enter one of the slots of that driven element; and the subsequent rotation of the shaft 230 will index the driven element 700 and the turret rotatable therewith. During that indexing, the turret will be rotated thirty six degrees and will present a fresh stack of cups to the sleeve 660.

Where the feeler 295 engages and is held by a cup, the pin 708 will move downwardly after it passes beyond the upper end of the rise 250 and before it passes under the driven element 700. If that pin does not do so in response to gravitational forces, it will be forced to do so by the inclined leading edge of the cam 498 on the lever 492. However, if the feeler 295 is not held by a cup, the pin 708 will be held in elevated position by the rise 250 as that pin approaches the periphery of the driven element 700; and that pin will engage the inclined leading edge of the cam 498 and rotate the lever 492 upwardly, thereby freeing the driven element 700. From this it will be apparent that the indexing step is substantially the same whether a six stack or a ten stack turret is being indexed.

Modified Headed Pin

FIGS. 33 and 34 show a modified form of headed pin that can be substituted for the headed pins 272 and 708. That pin is denoted by the numeral 716 and it is slidably held within a vertically-directed opening 718 in a ledge 720 of a disc 722. That disc is similar to the discs 264 and 702, but it has an outwardly-extending projection 724 on its hub. That projection has a horizontally-directed opening through it which receives a pin 726, and one end of that pin extends outwardly beyond one side of that projection. A spring 728 is wound around that one end of the pin 726, and it has one end thereof bearing against the bottom face of the disc 722. The other end of that spring extends through an opening 716 in the bottom of the pin 716; and that spring biases the pin 716 downwardly to place the head of that pin in abutting engagement with the top face of the ledge 720. Where the pin 716 is substituted for the pins 272 and 708, the cams 499 and 498 will not need to urge the pin 716 downwardly. In fact, where the disc 722 and pin 716 are substituted for either disc 264 and pin 272 or for disc 702 and pin 708, the lever 492 and the yoke 482 are not needed; the spring 728 providing the downward movement of the pin and the circular peripheries of the disc 722 and of the driven element 432 or 700 coating to

prevent rotation of the driven element as long as those peripheries are adjacent each other. However, the headed pins 272 and 708 and the lever 492 are preferred.

Modified Cup-Separating Fingers

FIGS. 35, 36 and 46-48 disclose cup-separating fingers that can be substituted for the cup-separating fingers 572 and 561; the cup-separating fingers that can be substituted for the cup-separating fingers 572 being denoted by the numeral 750, and the cup-separating fingers that can be substituted for the cup-separating fingers 561 being denoted by the numeral 760.

The cup-separating finger 750 has an upper portion that is similar to the cup-separating finger 572; having a reduced-height portion with a vertically-directed opening 751 therethrough, having a lip 754, having a flat upper face, and having a pin 752 that extends vertically upwardly from that flat face. However, that upper portion differs from the cup-separating finger 572 in having a downwardly-directed tubular portion 756 that has a threaded opening therein. That tubular portion 756 also has an upwardly-extending notch 758 at the lower face thereof. The opening 751 in the upper portion of the cup-separating finger 750 telescopes upwardly over the lower end of the pin 579, and that upper portion is held in engagement with that pin by the C-washers 582 and 583. At the same time, the pin 752 extends upwardly into the opening 564 of one of the cup-separating fingers 560 to hold the fingers 560 and 750 for conjoint rotation while permitting vertical movement of finger 750 relative to the finger 560.

The lower portion of the cup-separating finger 750 is a tubular extension 774 which has the same outer diameter as the tubular portion 756 of finger 750, which is provided with an upwardly-extending projection 776 dimensioned to fit into the notch 758 of that finger, which has a lip 780, and which has an axial passage 778. The lip 780 will be aligned with the lip 754 whenever the projection 776 is set in the notch 758; and the screw 782 extends upwardly through the passage 778 and seats in the threaded opening in the tubular portion 756 to hold that projection in that notch. When the screw 782 is fully seated, the extension 774 becomes, in effect, an integral part of the cup-separating finger 750.

The upper portion of the cup-separating finger 760 is generally similar to the cup-separating fingers 561; having an opening 762 to receive the shank of the pin 602, having a cylindrical portion that defines the opening 762 and is surrounded by a spring 764 identical to the spring 568, having a washer 766 staked or otherwise secured to the top of that cylindrical portion, and having a lip 768 identical with the lip 570 on finger 561. The upper portion of the cup-separating finger 760 differs from the fingers 561 in that it does not need an opening similar to the opening 564, and in that it has a downwardly-directed tubular portion 770. A threaded opening 771 is provided in the tubular portion 770; and a notch 772, comparable to the notch 758 in the tubular portion 756 of finger 750, is provided at the lower face of the tubular portion 770. The lower portion of the cup-separating finger 760 is a tubular extension 774 identical to the tubular extension 774 that is the lower portion of the cup-separating finger 750; and the projection 776 of that extension fits into the notch 772 to hold the lip 780 in register with the lip 768. The threaded opening in the tubular portion 770 of finger 760 receives the threaded shank of screw 782 to hold the extension 774 in assembled relation with the tubular portion 770. When so held, that tubular extension becomes, in effect, an integral part of the cup-separating finger 760.

The cup-separating fingers 750 and 760 are substituted for the cup-separating fingers 572 and 561 whenever the manufacturer or operator of a coin-operated, vending machine does not desire support 100 and closure 130. Those fingers will not only perform the cup-separating

functions of fingers 561 and 572, but they will also perform the cup-holding and cup-releasing functions of closure 130. Specifically, cup-separating fingers 750 and 760 will separate the lowermost cup of a stack of cups from that stack during a cycle of operation of the vending machine but will hold that cup against release to the cup-filling station of that machine until after the start of the next cycle of that machine.

Because support 100 is not used, tube 610 is not used; instead a tubular element 792 is used. As shown by FIG. 35, that tubular element has a horizontal flange 794 which underlies and supports cam ring 620; and that flange has an arcuate slot to accommodate set screw 623. The inner diameter of flange 794 and the inner diameter of tubular member 792 are larger than the inner diameters of flange 612 and tube 610; and those larger diameters make it possible for the tubular extensions 774 of fingers 750 and 760 to rotate freely. The tubular member 792 has a short tubular portion 796 that has an inner diameter comparable to that of tube 610.

The tubular member 792 is secured to and depends downwardly from the cup-separating head 500 of FIGS. 35 and 36; and that head is, with the exception of fingers 561 and 572 and of lever 304, identical to the cup-separating head 500 of FIGS. 1 and 2. That head has four stack-supporting fingers 587 mounted on its pins 584, and it has two cup-separating fingers 560 mounted on the sleeves 558. However, instead of having cup-separating fingers 572 mounted on the pins 579, the cup-separating head of FIGS. 35 and 36 has cup-separating fingers 750 mounted on those pins. Also, instead of having the fingers 561 mounted on the pins 602, the cup-separating head of FIGS. 35 and 36 has the fingers 760 mounted on those pins. Moreover, the pin 311 is set in the hole 732 of lever 304, thereby shifting the roller 314 to a set-back position.

To replace the head of FIGS. 1 and 2 with the head of FIGS. 35 and 36, it is only necessary to separate connecting rod 694 from pin 278 or pin 678, move the L-shaped fasteners 174 downwardly until the notches 176 at the upper ends thereof free the grooves in pins 512, pull the head 500 away from gear housing 144, shift disc 264 relative to shaft 230 approximately one hundred and five degrees counterclockwise, insert the pins 512 of the head of FIGS. 35 and 36 in openings 189 of gear housing 144, move the L-shaped fasteners 174 upwardly to lock those pins, and re-set connecting rod 694 on pins 278 and 678. The shifting of disc 264 relative to shaft 230 established a different normal position for the movable components of the head. Specifically, whereas sleeve 660 was close to the counterclockwise end of its path of oscillation, that sleeve is approximately midway between the ends of its path of oscillation when in the normal position of FIGS. 35 and 36. As a result, rollers 688 are spaced away from the vertical faces of stops 516, feeler 295 is disposed outwardly of the area defined by the inner periphery of sleeve 660, and abutments 665 have moved out of engagement with stack-supporting fingers 587 and have permitted those fingers to move into cup-engaging position. Thus, as shown by FIGS. 61 and 62, stack-supporting fingers 587 are in cup-engaging position and cup-separating fingers 750 are in raised position. In contrast, as shown by FIGS. 49 and 50, stack-supporting fingers 587 were not in cup-engaging position and cup-supporting fingers 572 were in lowered position. The roller 314 would, in that position, be holding the apron 318 out of engagement with the switch button 334 and would be holding feeler 317 too far out; but the roller 314, in its set back position, permits apron 318 to engage button 334 and permits feeler 317 to feel even the smallest diameter cups. In FIGS. 49 and 50 the separated cup 740 was resting upon and held by closure 130, whereas in FIGS. 61 and 62 the separated cup 786 is resting upon and supported by lips 780 of the tubular extensions 774. At this time, lips 570 and 768 of cup-separating fingers 560 and 760 support cup 788

by underlying the rim of that cup, and shoulders 596 of stack-supporting fingers 587 are above the rim of cup 786 but below the rim of cup 788.

When the motor in the motor housing 410 is energized by the insertion of a coin in the coin slot of the coin-operated, drink-dispensing vending machine, the shaft 230 will start to rotate in the counterclockwise direction and will cause the connecting rod 694 to rotate the sleeve 660 in the clockwise direction; and that rotation will cause the abutments 665 on the sleeve 660 to rotate the cup-separating fingers 560 and 760 toward the inner surface of the cylindrical body 502, and the cup-separating fingers 750 will rotate with the cup-separating fingers 560. As a result, the lips 570, 754, 768 and 780 will move out of the paths of the cups 786 and 788. Thereupon, the cup 786 will fall downwardly toward the cup-filling station in the coin-operated, drink-dispensing vending machine, and the cup 788 and the cups thereabove will be free to fall downwardly a short distance until they are held by the shoulders 596 on the four stack-supporting fingers 587. At this time, the cup 788 and the cups thereabove will be in the position shown by FIGS. 63 and 64. Further counterclockwise rotation of the shaft 230 will continue to rotate the sleeve 660 in the clockwise direction until the pin 278 on the disc 264 approaches one of its two dead centers; and after that pin has passed through that one dead center position, the sleeve 660 will start rotating in the counterclockwise direction. That rotation will move the abutments 665 on the sleeve 660 back out of engagement with the cup-separating fingers 560 and 760 and permit those fingers to return to the positions shown by FIGS. 65 and 66; and at that time the lips 570 and 768 will underlie the rim of the cup 790 and the lips 780 will underlie but be spaced a good distance below the rim of the cup 788. During this rotation, the stack-supporting fingers 587 remain in register with, and continue to support, the rim of the cup 788. Further rotation of the shaft 230 causes the sleeve 660 to continue to rotate in the counterclockwise direction and causes the abutment 665 thereon to rotate the stack-supporting fingers 587 out of register with the rim of the cup 788; and thereupon that cup will be free to fall downwardly until its rim engages and is supported by the lips 780 on the fingers 750 and 760, but as shown by FIG. 68, that cup may cling to the cup 790. The cup 790 and the cups thereabove will, however, move downwardly a short distance until they come to rest on the lips 570 and 768 of the fingers 560 and 760. Before the stack-supporting fingers 587 are returned to a position where they can re-engage the cup 788, the shaft 230 rotates the sleeve 660 still further in the counterclockwise direction and forces the rollers 688 to engage the vertical faces of stops 516 and then move downwardly and force the cup-separating fingers 750 downwardly to the position shown by FIG. 70. This downward movement of the fingers 750 occurs at the end of the counterclockwise rotation of the sleeve 660, and it occurs at a time when the abutments 665 on that sleeve are holding the stack-supporting fingers 587 close to the inner surface of the cylindrical wall 502 of the cup-separating head 500. As a result, whether the cup 788 falls downwardly and rests on the lips 780 of the fingers 750 and 760 immediately or whether that cup momentarily clings to the cup 790 and is subsequently forced downwardly by the lips 754 on the fingers 750, that cup will come to rest on, and be supported by, the lips 780 on the fingers 750 and 760, as shown by FIG. 70. The further counterclockwise rotation of the shaft 230 and of the disc 264 will cause the pin 278 to pass through its other dead center position and to start the sleeve 660 rotating again in the clockwise direction. After the shaft 230 has rotated approximately forty-five degrees, the fingers 750 will be permitted to move upwardly to the position of FIG. 72 where their lips 780 will help the lips 768 on the fingers 760 support the rim of the cup 790. Further counterclockwise rotation of the shaft 230 will rotate the sleeve 660 toward

its normal position; and in that position, the abutments 665 on that sleeve are out of engagement with the stack-supporting fingers 587 and those fingers are in the position shown by FIGS. 61 and 62.

It will be noted that whether or not the closure 130 is used, the cup dispenser provided by the present invention provides almost immediate delivery of a previously separated cup. Where the closure 130 is used, it is the movement of that closure to open position that releases the cup for delivery to the cup-filling station of the vending machine; but where the closure 130 is not used, it is the movement of the fingers 560 and 760 toward the inner surface of the cylindrical wall 502 of the body 500 that releases the lowermost cup. In both instances, that release occurs during the very early part of the cycle of the cup dispenser, and hence there will be ample time during the rest of that cycle for the cup-filling operations performed by the vending machine.

Where support 100 and closure 130 are used, the cup dispenser will usually be secured to the frame or other support in the vending machine by screws or bolts passing through the openings 131. However, where support 100 and closure 130 are not used, the cup dispenser will usually be secured to the frame or other support in the vending machine by screws passing through that frame or support and seating in the openings 155. In both instances, gear housing 144 supports the cup-separating head, the cam housing or housings, and the motor housing, as well as the turret.

Where support 100 and closure 130 are used, it is desirable to have tube 610 extend all the way down from the bottom of cylindrical wall 502 to support 100. Where that is done the lowermost cups are protected, both before and after they are separated from the stack. Furthermore, that tube holds the separated cup in register with discharge opening 104 and keeps it from moving rearwardly with closure 130. Because the distance between support 100 and the bottom of cylindrical wall 502 can be varied by aligning different pairs of openings 120 in the walls 114 with the openings 155 in the walls of gear housing 144, the tube 610 is made in three different lengths; and FIG. 2 shows a full length tube 610 while FIG. 1 shows a tube 610 of intermediate length. The fasteners 153 will be set in the appropriate openings in accordance with the request of the particular manufacturer of the coin-operated, vending machines, and thereafter the tube 610 of the required length will be secured to the head 500.

The arms 684 which carry the rollers 688 are always inclined downwardly from the horizontal, and they merely move further downwardly when they are pressed tightly against the vertical faces of the stops 516. The downward movement of those rollers, and hence of the pins 579 and of the cup-separating fingers thereon, is abrupt and rapid—occurring in less than ten degrees of rotation of the sleeve 660. That abrupt and rapid movement is desirable because it effectively separates any lowermost cup that tends to cling to the next higher cup, and it permits the other movements of the cup-separating fingers as well as the movements of the stack-supporting fingers to be made more slowly.

The springs 568 which bias the cup-separating fingers 560, 561 and 760 inwardly of the sleeve 660 apply inwardly directed forces to spaced areas on the upper portions of the lowermost and next-lowermost cups held within the head 500. However, those forces are not only resisted by the rigidity of the lowermost and next-lowermost cups but are also resisted by the rigidity of the cups stacked within that lowermost cup and within that next-lowermost cup. Consequently, the cups are able to successfully withstand the forces applied by the springs 568.

In FIGS. 1 and 2, the gear housing 144 has a cam housing 336 secured to it and has a motor housing 410 mounted in tandem with that cam housing. That arrangement is shown diagrammatically by FIG. 74. How-

ever, in some instances a cam housing will not be used; and in those instances the motor housing 410 will be secured directly to the gear housing 144. In other instances, as for example in FIGS. 73 and 75, a cam housing will be used in tandem with the cam housing and the two housings will be adjacent the left and right sides of the gear housing 144. In other instances, as for example in FIGS. 76, 77, 82, 83, 88 and 89, a cam housing and a motor housing are used and each of those housings is directly secured to the gear housing 144. In some instances, as for example in FIGS. 78, 84 and 90, two cam housings and a motor housing are secured directly to the gear housing 144. In other instances, as for example in FIGS. 29, 79, 80, 85, 86, 91 and 92, two cam housings and a motor housing are used, but that motor housing is mounted in tandem with a cam housing and is supported by that cam housing. In still other instances, as for example in FIGS. 81, 87 and 93, three cam housings are directly secured to the gear housing, and the motor housing is mounted in tandem with one of those cam housings. The resulting flexibility of mounting the cam housings and motor housing makes it possible to dispose the cup dispenser of the present invention in many different places in the vending machine.

In FIGS. 76, 77, 79, 80, 82, 83, 85, 86, 88, 89, 91 and 92, the shaft in one of the housings is equipped with a crown gear, comparable to the crown gear 350, that engages the lower set of teeth on the crown gear 238, while the shaft in the other housing is equipped with a gear, comparable to the crown gear 380, that engages the upper set of teeth on the crown gear 238.

In FIGS. 78, 81, 84, 87, 90 and 93, the shaft in one of the housings is equipped with a crown gear comparable to the crown gear 350, the shaft in another of the housings is equipped with a crown gear comparable to the crown gear 380, and the shaft in the third housing is also equipped with a crown gear comparable to the crown gear 386. The two crown gears 380 will be able to simultaneously engage the upper set of teeth on the crown gear 238 without interfering with each other. In those instances, as for example in FIGS. 73-75, where just one gear engages the crown gear 238, the sole function of the crown gear 238 is to transmit motion from the shaft of the cam housing to the shaft 230. Where, however, more than one crown gear engages the crown gear 238, the latter crown gear not only serves to rotate the shaft 230 but also serves to transmit force from the motor-driven shaft to one or more other shafts.

Where the cup dispenser is not provided with a cam housing, the gear housing 144 will be equipped with the switch 216. In those instances where the cup dispenser is provided with one or more cam housings, the gear housing need not, and usually will not, be equipped with the switch 216; and in such instances, one of the switches in one of the cam housings will perform the functions otherwise provided by switch 216.

Where the switch 216 is used, a notched rib can be substituted for the projection 244 on the crown gear 238. The rib on the gear 238 will engage the actuator 218 of switch 216 and hold that actuator down in all positions other than the normal, at rest position of the shaft 230. That switch will, unlike the switch of FIG. 13, be of the type that is closed when its actuator is held down and is open when its actuator is not held down; and, as a result, that switch will be open when the shaft is in its normal position and will be closed as soon as that shaft starts to rotate. Thereafter, that switch will remain closed until the notch again accommodates the actuator 218. Such an arrangement enables any failure of the switch actuator 218 to leave the switch 216 open, whereas any failure of the actuator 218 of FIG. 13 would leave the switch 216 closed.

As shown by the drawing, the positioning ring 634 limits the inward movement only of the stack-supporting members 587, and the cup-separating members 560 and

561 are free to move inwardly until they engage and are held by the cups. However, that positioning ring can, if desired, be made to limit the inward movement of the cup-separating members 560 and 561 as well; and this is easily done by removing portions of the stationary abutments 506 on the head 500 and by mounting pins on the ring 634 that occupy positions adjacent the positions presently occupied by those portions of the abutments 506. Those pins will be disposed radially inwardly of the circle defined by the pivots 558, 584 and 692 whereas the pins 636 are disposed radially outwardly of the circle; and, therefore, when the positioning ring 634 is rotated in the clockwise direction, the inner pins will move the fingers 560 and 561 outwardly while the pins 636 move the fingers 587 outwardly. The distances between the pivot-defined circle and the inner and outer pins on positioning ring 634 will be selected so that various fingers move the same distances when the positioning ring 634 is rotated.

As shown by the drawing, the stack-supporting fingers 587 are vertically adjustable but the cup-separating fingers 560 and 561 are held against vertical movement. However, if desired, the cup-separating fingers 560 and 561 could be mounted so they could be adjusted vertically.

Whereas the drawing and accompanying description have shown and described several preferred embodiments of the present invention, it should be apparent to those skilled in the art that various changes may be made in the form of the invention without affecting the scope thereof.

What I claim is:

1. A cup dispenser which comprises a support with a circular opening therethrough that is adapted to receive the lowermost cups of a vertically directed stack of cups, a plurality of vertically-directed pivots that are mounted on and depend downwardly from said support and that are positioned around said opening, a plurality of cup-separating fingers rotatably mounted on said pivots for rotation into and out of cup-engaging position, a plurality of springs biasing said cup-separating fingers toward cup-engaging position, a second plurality of vertically-directed pivots that are mounted on and depend downwardly from said support and that are positioned around said opening, said second plurality of pivots being interleaved with the first said plurality of pivots, a plurality of stack-supporting fingers rotatably mounted on said second plurality of pivots for rotation into and out of stack-supporting position, a second plurality of springs biasing said stack-supporting fingers toward stack-supporting position, said cup-separating fingers and said stack-supporting fingers being spaced apart axially of said support opening, a cylindrical member that is rotatably mounted in said circular opening in said support and that has circumferentially-spaced, finger-engaging abutments thereon, said cylindrical member being rotatable in one direction to move some edges of said abutments against said cup-separating fingers and thereby move said cup-separating fingers against the bias of said plurality of springs and out of cup-engaging position, said cylindrical member being rotatable in the opposite direction to move other edges of said abutments against said stack-supporting fingers to move said stack-supporting fingers against the bias of said second plurality of springs and out of stack-supporting position, a positioning ring that encircles but is spaced radially outwardly of said circular opening, said positioning ring having surfaces thereon that can coact with surfaces on said stack-supporting fingers to limit rotation of said stack-supporting fingers toward stack-supporting position, said positioning ring being movable circumferentially of said support opening to vary the extent to which said stack-supporting fingers can move to stack-supporting position, a panel adjacent said support, a cam that is rotatable relative to said support and relative to said panel, and a lever that is rotatable with said cam and that is adjacent said panel, said panel having markings thereon, said lever being rotatable relative to said

panel to rotate said cam relative to said support and thereby shift said positioning ring circumferentially of said support to vary the extent to which said stack-supporting fingers can move to stack-supporting position.

2. A cup dispenser which comprises a support with a circular opening therethrough that is adapted to receive the lowermost cups of a vertically-directed stack of cups, a plurality of vertically-directed pivots that are mounted on and depend downwardly from said support and that are positioned around said opening, a plurality of cup-separating fingers rotatably mounted on said pivots for rotation into and out of cup-engaging position, a plurality of springs biasing said cup-separating fingers toward cup-engaging position, a second plurality of vertically-directed pivots that are mounted on and depend downwardly from said support and that are positioned around said opening, said second plurality of pivots being interleaved with the first said plurality of pivots, a plurality of stack-supporting fingers rotatably mounted on said second plurality of pivots for rotation into and out of stack-supporting position, a second plurality of springs biasing said stack-supporting fingers toward stack-supporting position, said cup-separating fingers and said stack-supporting fingers being spaced apart axially of said support opening, a cylindrical member that is rotatably mounted in said circular opening in said support and that has circumferentially-spaced, finger-engaging abutments thereon, said cylindrical member being rotatable in one direction to move some edges of said abutments against said cup-separating fingers and thereby move said cup-separating fingers against the bias of said plurality of springs and out of cup-engaging position, said cylindrical member being rotatable in the opposite direction to move other edges of said abutments against said stack-supporting fingers to move said stack-supporting fingers against the bias of said second plurality of springs and out of stack-supporting position, and a positioning ring that encircles but is spaced radially outwardly of said circular opening, said positioning ring having surfaces thereon that can coat with surfaces on said stack-supporting fingers to limit rotation of said stack-supporting fingers toward stack-supporting position, said positioning ring being movable circumferentially of said support opening to vary the extent to which said stack-supporting fingers can move to stack-supporting position.

3. A cup dispenser which comprises a support with a circular opening therethrough that is adapted to receive the lowermost cups of a vertically-directed stack of cups, a plurality of vertically-directed pivots that are mounted on and depend downwardly from said support and that are positioned around said opening, a plurality of cup-separating fingers rotatably mounted on said pivots for rotation into and out of cup-engaging position, a plurality of springs biasing said cup-separating fingers toward cup-engaging position, a second plurality of vertically-directed pivots that are mounted on and depend downwardly from said support and that are positioned around said opening, said second plurality of pivots being interleaved with the first of said plurality of pivots, a plurality of stack-supporting fingers rotatably mounted on said second plurality of pivots for rotation into and out of stack-supporting position, a second plurality of springs biasing said stack-supporting fingers toward stack-supporting position, said cup-separating fingers and said stack-supporting fingers being spaced apart axially of said support opening, a cylindrical member that is rotatably mounted in said circular opening in said support and that has circumferentially-spaced, finger-engaging abutments thereto, said cylindrical member being rotatable in one direction to move some edges of said abutments against said cup-separating fingers and thereby move said cup-separating fingers against the bias of said plurality of springs and out of cup-engaging position, said cylindrical member being rotatable in the opposite direction to move other edges of said abutments against said stack-supporting fingers to move said stack-supporting fingers against the bias of said second

plurality of springs and out of stack-supporting position, said stack-supporting fingers being vertically movable relative to said second plurality of pivots, a third plurality of springs biasing said stack-supporting fingers downwardly relative to said second plurality of pivots but being yieldable to permit upward movement of said stack-supporting fingers relative to said second plurality of pivots, a cam ring with a plurality of dwells and a plurality of shallow, inclined rises thereon, a member that can engage said stack-supporting fingers and that can be moved by said cam ring, said cam ring being rotatable to move said member and thereby move said stack-supporting fingers vertically relative to said second plurality of pivots, a set screw to releasably hold said cam ring against rotation, and a panel with markings thereon that coat with said set screw to indicate the vertical positions of said stack-supporting fingers.

4. A cup dispenser which comprises a support with a circular opening therethrough that is adapted to receive the lowermost cups of a vertically-directed stack of cups, a plurality of vertically-directed pivots that are mounted on and depend downwardly from said support and that are positioned around said opening, a plurality of cup-separating fingers rotatably mounted on said pivots for rotation into and out of cup-engaging position, a second plurality of vertically-directed pivots that are mounted on and depend downwardly from said support and that are positioned around said opening, said second plurality of pivots being interleaved with the first said plurality of pivots, a plurality of stack-supporting fingers rotatably mounted on said second plurality of pivots for rotation into and out of stack-supporting position, a second plurality of springs biasing said stack-supporting fingers toward stack-supporting position, said cup-separating fingers and said stack-supporting fingers being spaced apart axially of said support opening, a cylindrical member that is rotatably mounted in said circular opening in said support and that has circumferentially-spaced, finger-engaging abutments thereon, said cylindrical member being rotatable in one direction to move some edges of said abutments against said cup-separating fingers and thereby move said cup-separating fingers against the bias of said plurality of springs and out of cup-engaging position, said cylindrical member being rotatable in the opposite direction to move other edges of said abutments against said stack-supporting fingers to move said stack-supporting fingers against the bias of said second plurality of springs and out of stack-supporting position, and said stack-supporting fingers being vertically movable relative to said second plurality of pivots, a third plurality of springs biasing said stack-supporting fingers downwardly relative to said second plurality of pivots but being yieldable to permit upward movement of said stack-supporting fingers relative to said second plurality of pivots, a cam ring with a plurality of dwells and a plurality of shallow, inclined rises thereon, a member that can engage said stack-supporting fingers and that can be moved by said cam ring, said cam ring being rotatable to move said member and thereby move said stack-supporting fingers vertically relative to said second plurality of pivots.

5. A cup dispenser which comprises a support with a circular opening therethrough that is adapted to receive the lowermost cups of a vertically-directed stack of cups, a plurality of vertically-directed pivots that are mounted on and depend downwardly from said support and that are positioned around said opening, a plurality of cup-separating fingers rotatably mounted on said pivots for rotation into and out of cup-engaging position, a plurality of springs biasing said cup-separating fingers toward cup-engaging position, a second plurality of vertically-directed pivots that are mounted on and depend downwardly from said support and that are positioned around said opening, said second plurality of pivots being interleaved with the first said plurality of pivots, a plurality of stack-supporting fingers rotatably mounted on said second plurality of pivots for rotation into and out of stack-supporting position, a second plurality of springs biasing said stack-supporting fingers toward stack-supporting position, said cup-separating fingers and said stack-supporting fingers being spaced apart axially of said support opening, a cylindrical member that is rotatably mounted in said circular opening in said support and that has circumferentially-spaced, finger-engaging abutments thereto, said cylindrical member being rotatable in one direction to move some edges of said abutments against said cup-separating fingers and thereby move said cup-separating fingers against the bias of said plurality of springs and out of cup-engaging position, said cylindrical member being rotatable in the opposite direction to move other edges of said abutments against said stack-supporting fingers to move said stack-supporting fingers against the bias of said second

5 fingers rotatably mounted on said second plurality of pivots for rotation into and out of stack-supporting position, a second plurality of springs biasing said stack-supporting fingers toward stack-supporting position, a cylindrical member that is rotatably mounted in said circular opening in said support and that has circumferentially-spaced finger-engaging abutments thereon, said cup-separating fingers and said stack-supporting fingers being spaced apart axially of said support opening, said cylindrical member being rotatable in one direction to move some edges of said abutments against said cup-separating fingers and thereby move said cup-separating fingers against the bias of said plurality of springs and out of cup-engaging position, said cylindrical member being rotatable in the opposite direction to move other edges of said abutments against said stack-supporting fingers to move said stack-supporting fingers against the bias of said second plurality of springs and out of stack-supporting position, a positioning ring that encircles but is spaced radially outwardly of said circular opening, said positioning ring having surfaces thereon that can coact with surfaces on said stack-supporting fingers to limit rotation of said stack-supporting fingers toward stack-supporting position, said positioning ring being movable circumferentially of said support opening to vary the extent to which said stack-supporting fingers can move to stack-supporting position, a panel adjacent said support, a cam that is rotatable relative to said support and relative to said panel, a lever that is rotatable with said cam and that is adjacent said panel, said panel having markings thereon, said lever being rotatable relative to said panel to rotate said cam relative to said support and thereby shift said positioning ring circumferentially of said support to vary the extent to which said stack-supporting fingers can move to stack-supporting position, said stack-supporting fingers being vertically movable relative to said second plurality of pivots, a third plurality of springs biasing said stack-supporting fingers downwardly relative to said second plurality of pivots but being yieldable to permit upward movement of said stack-supporting fingers relative to said second plurality of pivots, a cam ring with a plurality of dwells and a plurality of shallow, inclined rises thereon, said cam ring being rotatable to move said positioning ring and thereby move said stack-supporting fingers vertically relative to said second plurality of pivots and a set screw to releasably hold said cam ring against rotation, some of said markings on said panel coacting with said lever to indicate the positions normally occupied by said stack-supporting fingers, other of said markings on said panel coacting with said set screw to indicate the vertical positions of said stack-supporting fingers.

6. A cup dispenser which comprises a support with a circular opening that is adapted to receive the lowermost cups of a vertically-directed stack of cups, a plurality of pivots that are stationary relative to said support and positioned around said opening, a plurality of cup-separating fingers rotatably mounted on said pivots for rotation into and out of cup-engaging position, a second plurality of pivots that are stationary relative to said support and positioned around said opening, a plurality of stack-supporting fingers rotatably mounted on said second plurality of pivots for rotation into and out of stack-supporting position, said cup-separating fingers and said stack-supporting fingers being spaced apart axially of said support opening, a positioning ring having surfaces that can coact with surfaces on said stack-supporting fingers to limit rotation of said stack-supporting fingers toward stack-supporting position, said positioning ring being movable circumferentially of said support to vary the extent to which said stack-supporting fingers can move to stack-supporting position, said stack-supporting fingers being vertically movable relative to said second plurality of pivots, a plurality of springs biasing said stack-supporting fingers downwardly relative to said second plurality of pivots but being yieldable to permit upward movement of

said stack-supporting fingers relative to said second plurality of pivots, and a cam ring with a plurality of vertically-spaced dwells, said cam ring being rotatable to move said positioning ring and thereby move said stack-supporting fingers vertically relative to said second plurality of pivots.

7. A cup dispenser which comprises a support with a circular opening that is adapted to receive the lowermost cups of a vertically-directed stack of cups, a plurality of vertically-directed pivots mounted on and depending downwardly from said support and positioned around said opening, a plurality of cup-separating fingers rotatably mounted on said pivots for rotation into and out of cup-engaging position, a plurality of springs biasing said cup-separating fingers toward cup-engaging position, a second plurality of vertically-directed pivots mounted on and depending downwardly from said support and positioned around said opening, a plurality of stack-supporting fingers rotatably mounted on said second plurality of pivots for rotation into and out of stack-supporting position, a second plurality of springs biasing said stack-supporting fingers toward stack-supporting position, said cup-separating fingers and said stack-supporting fingers being spaced apart axially of said support opening, and an adjustably mounted stop that limits rotation of said stack-supporting fingers toward stack-supporting position, whereby said cup dispenser can accommodate stacks of cups having different diameters, said stop being a circumferentially movable positioning ring with surfaces thereon that can receive and hold portions of said stack-supporting fingers.

8. A cup dispenser which comprises a support with a circular opening that is adapted to receive the lowermost cups of a vertically-directed stack of cups, a plurality of vertically-directed pivots mounted on and depending downwardly from said support and positioned around said opening, a plurality of cup-separating fingers rotatably mounted on said pivots for rotation into and out of cup-engaging position, a plurality of springs biasing said cup-separating fingers toward cup-engaging position, a member that is selectively rotatable to move spaced surfaces thereon against said cup-separating fingers and thereby move said cup-separating fingers against the bias of said plurality of springs and out of cup-engaging position, a second plurality of vertically-directed pivots mounted on and depending downwardly from said support and positioned around said opening, a plurality of stack-supporting fingers rotatably mounted on said second plurality of pivots for rotation into and out of stack-supporting position, a second plurality of springs biasing said stack-supporting fingers toward stack-supporting position, said member having other spaced surfaces thereon that are selectively movable against said stack-supporting fingers to move said stack-supporting fingers against the bias of said second plurality of springs and out of stack-supporting position, and an adjustably mounted stop that limits rotation of said stack-supporting fingers toward stack-supporting position, whereby said cup dispenser can accommodate stacks of cups having different diameters, said stop being a circumferentially movable positioning ring with surfaces thereon that can receive and hold portions of said stack-supporting fingers.

9. A cup dispenser which comprises a support with an opening therethrough that is adapted to receive the lowermost cups of a vertically-directed stack of cups, a pivot mounted on said support adjacent said opening, a cup-separating finger rotatably mounted on said pivot for rotation into and out of cup-engaging position, a second pivot mounted on said support adjacent said opening, a stack-supporting finger rotatably mounted on said second pivot for rotation into and out of stack-supporting position, an adjustably mounted stop that limits rotation of one of said fingers toward the cups to be dispensed, whereby said cup dispenser can accommodate stacks of cups having different diameters, a cam to adjust the position of said stop, a lever to move said cam and thereby move said

stop, and a panel adjacent said lever, said panel having markings thereon that coat with said lever to indicate the position of said one finger.

10. A cup dispenser which comprises a support with an opening therethrough that is adapted to receive the lowermost cups of a vertically-directed stack of cups, a hollow pivot mounted on said support adjacent said opening, a second pivot that is telescoped within said hollow pivot and that is movable axially relative to said hollow pivot, a cup-separating finger rotatably mounted on the first said pivot for rotation into and out of cup-engaging position, a second cup-separating finger rotatably mounted on said second pivot for rotation into and out of cup-engaging position, a pin on one of said fingers and a complementary opening in the other of said fingers to hold said fingers for conjoint rotation, said pin being longer than the length of relative axial movement of said fingers, and lips on said fingers.

11. A cup dispenser which comprises a support with an opening therethrough that is adapted to receive the lowermost cups of a vertically-directed stack of cups, a pivot mounted on said support adjacent said opening, a second pivot that is concentric with the first said pivot and that is movable axially relative to said first pivot, a cup-separating finger rotatably mounted on the first said pivot for rotation into and out of cup-engaging position, a second cup-separating finger rotatably mounted on said second pivot for rotation into and out of cup-engaging position, interacting surfaces on said cup-separating fingers that hold said fingers for conjoint rotation while permitting relative axial movement of said fingers.

12. A cup dispenser which comprises a stationary support with a circular opening that is adapted to receive the lowermost cups of a vertically-directed stack of cups, a hollow pivot mounted on said support adjacent said opening, a cup-separating finger that is rotatably mounted on said pivot but is held against appreciable vertical movement, a second pivot that is telescoped within the first said pivot and is movable vertically relative to the first said pivot and thus axially of said opening, a second cup-separating finger that is rotatably mounted on said second pivot and is held against appreciable vertical movement relative to said second pivot, a sleeve rotatably mounted

for rotation relative to said support, an arm rotatably mounted on said sleeve, a roller carried by said arm, a stop on said sleeve that holds said arm inclined downwardly below the horizontal, a second stop on said support, said second stop being adjacent said second pivot, said sleeve being rotatable relative to said support to move said roller into engagement with said second stop and thereby force said roller to rotate downwardly with said arm and to force said second pivot downwardly to force said second cup-separating finger downwardly and away from the first said cup-separating finger, and interacting surfaces on said cup-separating fingers that hold said cup-separating fingers for conjoint rotation while permitting relative vertical movement of said cup-separating fingers.
